UNITED STATES PATENT OFFICE

WILLIAM HUGO MATTHIES, OF ANTWERP, BELGIUM, ASSIGNEE TO WESTERN ELECTRIC COMPANY, OF NEW YORK, N. Y., A CORPORATION OF ILLINOIS.

TELEPHONE-EXCHANGE SYSTEM.

1,161,874.

Specification of Letters Patent. Patented Nov. 30, 1915.

Application filed November 4, 1910. Serial No. 530,650.

To all whom it may concern:

Be it known that I, WILLIAM HUGO MATTHIES, citizen of the United States, residing at Antwerp, in the Province of Antwerp and Kingdom of Belgium, have invented a certain new and useful Improvement in Telephone-Exchange Systems, of which the following is a full, clear, concise, and exact description.

10 My invention relates to telephone exchange systems and contemplates in general an improved organization and arrangement of circuits and apparatus whereby the interconnection of telephone lines and trunk lines 15 may be controlled and accomplished speedily and with precision.

One of the features of this invention resides in the provision of circuits and apparatus whereby a connecting circuit may be 20 extended by causing an automatic finder switch to hunt for and make connection to the terminals of said circuit at the called or outgoing end thereof.

Another feature of the invention resides 25 in the arrangement of the finder switches in groups and the provision of group selecting means for causing a switch of any desired group to make connection to the outgoing end of a connecting circuit.

30 A still further feature of this invention resides in the provision of sending devices at the central office which are arranged to be set by impulses transmitted from an outgoing station to govern the operation of the 35 group selecting means.

A further object of my invention is to provide a system comprising mechanical switching apparatus adapted to connect telephone lines and trunk lines and to interconnect the same, and in which such telephone lines or trunk lines are or may be, or a part of them are or may be, connected or arranged according to some other system than the decimal system of notation, means 40 whereby impulses sent from a primary controller and designed to accomplish the connection of a desired line, which impulses are arranged according to the decimal system of notation, may be in effect so modified or re- 45 arranged by a secondary controller that the operation of the mechanical switching apparatus may be controlled to accomplish the desired connection speedily and with absolute precision.

My invention also contemplates the provision in a system involving mechanical switching apparatus of a new and improved system and arrangement whereby such switching apparatus may be simplified in construction, lessened in cost and increased 60 in efficiency without any loss whatever in the speed or precision of its operation and with a decrease in the amount of such apparatus necessary for use in a system of any given extent.

65 My invention is shown as applied to a full automatic telephone exchange system, but it should be understood that while it is particularly adapted to and has been found especially efficient in connection with full 70 automatic systems, my invention is not confined to use in such systems, but may be advantageously used in connection with any or all systems involving mechanical switching apparatus which must be rapidly and accurately controlled.

I have furthermore shown my invention in connection with mechanical switching apparatus of a particular form, but it will be apparent that it is not confined to use in connection with switching apparatus of this type, but may be used with any switching apparatus of suitable or convenient structure and arrangement. Furthermore, while the mechanical switching apparatus in connection with which I have shown my invention is controlled according to what is known as the reverte impulse system of control, it must be understood that my invention is not limited to such system of control, but may, 80 if desired, be used in connection with switching apparatus designed to be controlled by impulses received from the controlling apparatus, as will be hereinafter pointed out.

85 My invention also includes certain details of the construction and organization of the circuits and apparatus involved in my improved controlling system by which the foregoing results and operations, and other results and operations incidental to the proper 90 and expeditious accomplishment of the interconnection of telephone lines and trunk lines in systems of the character indicated may be best accomplished.

95 The accompanying drawings which illustrate the preferred form of my invention show as portions thereof features which in themselves form no part of my present in-

vention and are not therefore claimed in this application. These features are claimed in my Patent No. 996,500.

In the drawings Figures 1, 2, 3, 4 and 5, when placed together form a single diagram illustrating diagrammatically the circuits and apparatus involved in a full automatic exchange system comprising in part the system of control in accordance with my invention; the lines which extend to the edge of each sheet being continued on the neighboring sheets. The proper arrangement of the sheets for viewing the system as a whole is made by placing Figs. 1, 2, 3 and 4 in line horizontally from left to right respectively, and placing Fig. 5 immediately below Fig. 2. Fig. 6 is a front view of one of the register senders or register controllers of the character adapted to be used in my invention and form a part of what is known as the secondary controller therein. Fig. 7 shows a modified form of register sender.

Like parts are referred to by the same reference characters throughout the specification.

Line finders.—A part of the apparatus involved in the preferred form of my invention and as shown in the drawings herein comprises a series of line finders such as are shown to the left of Fig. 2 on the upper part thereof, to the left of Fig. 3 on the upper part thereof, to the left of Fig. 4 on the upper part thereof and in the right-hand upper corner of Fig. 5. These line finders may be of any usual or convenient construction, but each comprises preferably a set of three brushes adapted to be rotated to sweep over any desired and convenient number of sets of line terminals, each such set of terminals comprising three terminals, that is, two line terminals and a test terminal, such brushes being driven by a power magnet indicated, for example, in Fig. 2 as 259. This power magnet may cause the rotation of the brushes over the terminals in any desired manner, but preferably operates to drive such brushes by means of an electromagnetic clutch, such as is well known to the art and therefore need not be further described. Furthermore, associated with each of these line finders is a finder holding magnet which, when it is deenergized, is adapted to hold the finder brushes in the position to which they have been driven, such holding magnet operating by means of a mechanical centering clutch to center the brushes upon the terminals with which they have come in contact, as is well understood, or in any other desired or preferred manner. The operation of these line finders will therefore be seen to be accomplished through the energization of the finder rotary magnet as 259 and the finder holding magnet as 260 which may be energized in parallel as shown. When these magnets are energized the brushes will be-

gin to rotate, sweeping over the contact terminals of the various sets of terminals which appear in the particular line finder until the deenergization of the finder rotary magnet and the finder holding magnet, when they will stop and the finder brushes will remain in contact with the terminals of the particular line with which they are connected at this time until the subsequent energization of the finder rotary magnet and the finder holding magnet. It should be further noted that for the purposes to be hereinafter described, the test brush of the respective line finders is made of elongated form so that it will make contact with the test terminal of one set of terminals before breaking contact with the test terminal of the preceding set. The line brushes, however, will not bridge from one line terminal to the next.

Sequence switches.—The local controlling circuits associated with the various parts of the exchange system disclosed herein, which local controlling circuits must be established in definite order at successive stages of the operation of such system to bring into service the different devices or parts as they are required, are in the present embodiment of my invention established by automatic electromechanical switching appliances which are termed sequence switches. As will be noted by reference to the drawing, there is a sequence switch 201 associated with the primary finder apparatus, a sequence switch 501 associated with the secondary controller apparatus, a sequence switch 301 associated with the intermediate finder apparatus and a sequence switch 401 associated with the final finder apparatus and its associated selector. Each of these sequence switches consists in its elements of a movable switch operating member, a number of circuit changers or contact devices actuated in sequence as said member is moved from one position to another, an electromagnet and a motor mechanism operated or controlled by said magnet for advancing said movable member through its successive positions.

The sequence switch may control any desired sequence of operations, whether of the same or different devices. In each position to which this movable member is advanced, a circuit is established whereby a given operation of the device or devices under control is made possible, and at the same time another circuit is established whereby the motor mechanism of the sequence switch may be actuated automatically when such operation of the device or devices under control has been completed; so that as each operation takes place the sequence switch will be automatically moved to the next position, in which position a new operation or another stage of the same operation will be brought about and so on. Finally the sequence switch establishes a condition where-

by the apparatus under control is returned to its normal condition, and also establishes a circuit whereby the sequence switch will be returned to its normal position. In each such position, the apparatus and its associated sequence switch may be and are preferably so related that local reciprocal controlling circuits will be progressively established by said devices in their operation, 10 in such a manner that when a normal operation of either is started both devices will be progressively carried through a complete cycle of operations which may be controlled and checked at different stages through the agency of energizing circuits established by some other portion of the apparatus for this purpose, but which unless so checked will terminate in the automatic return of both the sequence switch and its associated apparatus to normal condition. In case of a 20 failure of current in such checking or controlling circuit, even immediately after a sequence switch and its associated apparatus have started in operation, such sequence switch and apparatus cannot become permanently displaced or stalled in an off normal condition but will complete their cycle of operations and be positively returned to normal under control of circuits which are 25 purely local.

In the circuit diagram herein illustrating my invention, the switch springs of the sequence switches are not shown in their actual arrangement, but are so located as to give the 30 clearest arrangement of circuits. Furthermore, the operating cams are not shown. The positions of the rotary element of each sequence switch, in which any of its contacts are closed, are indicated by numbers 35 placed adjacent to such contacts, each contact, except the special contacts which will be hereinafter referred to, being open in all positions except those indicated by the adjacent numbers. For convenience, the sequence switch contacts may be identified 40 with their sequence switch power apparatus, indicated upon the diagrammatic showing, by the fact that the hundreds digit of the reference character applied to each sequence 45 switch contact is the same as the hundreds digit of the reference character applied to the sequence switch of which it forms a part. It will furthermore be observed that the sequence switch contacts on any sheet are all 50 controlled and operated by the sequence switch power apparatus shown upon the same sheet; for example, all sequence switch contacts the hundreds digit of whose reference character is 2, form a part of the 55 sequence switch 201 which is shown upon the same sheet. Each sequence switch has, 60 however, as has been before noted, a special contact governing the local circuit of its motor magnet. As these special contacts, 65 which are represented by the contacts 202,

302, 402 and 502 of the respective sequence switches 201, 301, 401 and 501 upon the drawings are closed only while the rotary element of the sequence switch is in transit from one stopping position to the next, the 70 numbers are placed on the side of the switch lever opposite from the contact and indicate the positions in which such contact is open, such contact being closed at all times while the rotary element is in transit between the positions indicated by the numbers. Thus by reference to the numerals 1, 6, 8, 9, 10, 12, 14, 16, 18, appearing adjacent to the switch lever of the special contact 202 of the sequence switch 201, it is 80 seen that this contact is open in the first position of this sequence switch, closed continuously between the first and sixth positions, open in the sixth position, closed continuously between the sixth and eighth positions, open in the eighth position, closed 85 between the eighth and ninth positions, open in the ninth position and so on. This contact being closed, for example, between the first and sixth positions, the sequence switch 90 will not stop in its second, third, fourth or fifth positions, but will stop again only when the special contact 102 opens and then only provided that some other energizing circuit has not meanwhile been closed. The numerals adjacent to these special contacts 95 of the various sequence switches indicate therefore the only positions in which their associated sequence switches are adapted to stop. Since, however, the sequence switches 100 of the character described are known to the art, the particular structure and arrangement of the form used and shown in the preferred form of my invention need not be particularly described and any form thereof 105 which may be suitable or convenient may be used.

Wet point mechanisms.—The wet point mechanisms which are shown to the right of Figs. 2 and 3 partake somewhat of the nature of sequence switches. They comprise each a rotatable spindle, the movement of which is adapted to be controlled by an electromechanical clutch, power being preferably supplied from a constantly rotating 110 shaft precisely as is the case in the sequence switches shown herein. Upon the energization of the power magnet, therefore, the spindle will be rotated, such spindle carrying thereon means whereby the contact devices, shown immediately above the power magnet and portion of the spindle upon the drawings, will be operated, one set of said contact devices being operated in each position or stage of the rotation of the spindle 115 120 and one set only. Each set of contact devices comprises, as is plainly shown upon the drawing, a test conductor terminal and a local conductor terminal.

Associated with the test conductor ter- 125 130

- 5 minal is a normal ground connection and an alternate connection leading to sequence switch contacts, and associated with the local conductor terminal is an alternate connection leading to other sequence switch contacts. When, for example, the wet point device spindle is in its first position after leaving its normal position, the ground connection will be removed from the test conductor terminal 279 of the first group of contacts and the alternate terminal be connected therewith, and also the terminal 282 will be connected with the local conductor terminal 297 of the same group of contacts.
- 10 15 When the wet point device spindle by its further movement has reached its second position, the contacts of the first group have been restored to their normal condition and the contacts of the second group are now 20 operated and so on, there being as many groups of contact devices as may be desired. As soon as the wet point device spindle moves out of its first position, moreover, there is a contact 283 closed known as the 25 off normal switch. This switch will be closed at all times except when the wet point device spindle is in its normal position for purposes which will be hereinafter described. Furthermore, there is associated with each 30 wet point device an interrupter shown in Fig. 2 as 284, the contacts of which are adapted to be opened in the normal position of the wet point device spindle and in each of the positions in which the different sets of 35 contact devices are operated by the spindle, but are closed at all times during the movement of such wet point device spindle from one position to the next, for example, in its movement from its normal position to its 40 first position and in the movement from its first position to its second position and so on. Since, however, the particular structure of the wet point devices forms no part of my invention, it need not be further described, 45 it only being necessary that the apparatus used in this particular connection performs the functions stated in a similar or equivalent manner.
- 50 *Register senders.*—The register senders used in the secondary controller forming a part of my invention may be of the form shown in Fig. 6. This form of register sender comprises a disk 76 rotatably mounted upon a shaft 77 and having upon the periphery thereof two sets of oppositely inclined ratchet teeth 78 and 79. Adapted to cooperate with the ratchet teeth 78 and in such cooperation to drive the disk 76 in a clockwise direction, is the pawl 80 mounted, 55 as is clearly shown, upon the armature 81 of the magnet 82 of which only the pole pieces are shown. Cooperating, on the other hand, with the ratchet teeth 79 and in such cooperation adapted to drive the disk in a 60 counter-clockwise direction, is the pawl 83

65 mounted, as is clearly shown, upon the armature 84 of a magnet 85 of which only the pole pieces are shown. Mounted upon the disk 76 is an insulated stud 86 which, in the normal position of the register disk forces 70 the light spring 87 into contact with the contact spring 88 and out of contact with the contact spring 89. When, however, the register disk 76 is moved from its normal position, the contact spring 87 will no longer 75 make contact with the spring 88 but will be in contact with the spring 89 and only be restored to contact with the spring 88 when the register disk is again fully in its normal position. There is also shown in this 80 figure a friction brake 90 adapted, under the tension of the spring 91, to cooperate with the shaft 77 or a part carried thereon in such manner that while the shaft and the supported disk 76 may be rotated in either 85 a clockwise or counter clockwise direction, it will stay in any position to which it is driven, and in being driven to such position will not overthrow or run by. This construction, however, is so obvious and usual 90 that it need not be further described. There is also shown in this register sender a brass stop plate 92 which by cooperation with the lug 93 prevents the movement of the disk 76 by any unusual or external operation beyond 95 what may be considered its normal limits. There also appears in the register sender shown various means such as springs, stops, etc., for controlling the proper operation of the pawls and armatures, but since the co-operation of these parts is so clearly shown upon the drawings and is so well known to those skilled in the art they need not be described in detail.

100 It will be obvious that upon the energization 105 of the magnet 82, the armature 81 will be attracted and in the movement of such armature the pawl 80 will drive the register disk 76 one step in a clockwise direction. This movement of the register disk will open 110 the contacts 87 and 88 and close the contacts 87 and 89. When the magnet 82 again is deenergized and the armature 81 is thereby released the pawl 80 will be retracted preparatory to a second operating movement 115 in response to a second energization of the magnet, but the register disk 76 will remain one step from its normal position. Upon the second energization of the same magnet, the armature 81 will be again attracted and the pawl 80 will drive the register disk in a clockwise direction a second step from its normal position. That is to say, in response to each energization of this magnet 82 the register disk 76 will be driven 120 one step in a clockwise direction. This is the "setting" operation of the register disk.

125 The register disk having been thus set or adjusted the manner of its return to its normal position will be described. To ac- 130

complish this return, the magnet 85 will be operated thereby attracting the armature 84 which in its movement will cause the pawl 83 to coöperate with the teeth 79 of the register disk and in such coöperation drive the disk in a counter-clockwise direction one step toward its normal position. Upon the deenergization of the magnet 85 the armature 84 and the pawl 83 will be retracted and 5 prepare themselves to drive the register disk 76 a second step in a counter-clockwise direction toward its normal position upon a subsequent energization of the magnet 85. It will be apparent, therefore, that with the 10 particular arrangement of pawls and teeth shown, it will require the same number of energizing impulses through the magnet 85 to restore the register disk to its normal position as passed through the magnet 82 to 15 set the register disk in its set position. When, therefore, the same number of energizing impulses have passed through the magnet 85 as have previously passed through the magnet 82, the register disk 76 will 20 again be in its normal position and the contacts 87, 89 will be again opened and the contacts 87 and 88 be again closed. The detailed operation of these register senders as applied to the system embodying my invention as shown herein will further appear in the description of the operation of such system.

The modified form of register sender shown in Fig. 7, shows a register sender 25 adapted for what is known as the direct system of control for mechanical switching apparatus rather than the revertive impulse system of control, to which form of control the register sender shown in Fig. 6 is particularly adapted, and the form shown in Fig. 7 furthermore indicates a register sender constructed and arranged to embody, when used as a part of a system, what is known as translation. That is to say, impulses received which energize the magnet 82 will set the register disk 76 in precisely the same manner as in the register sender shown in Fig. 6, but after the register disk has been set, instead of requiring the receipt of impulses of the same number as were received over the magnet 82 to restore the register disk, such register disk may be mechanically coupled by any preferred means and at any desired time to the constantly rotating shaft 98 shown in dotted lines on Fig. 7, and will send out or transmit impulses in its return to normal driven by such shaft, such impulses being, if desired, of a different or translated number or arrangement from those received by the register.

In the form shown in Fig. 7 the register disk 76 is provided on the portion opposite the ratchet teeth 78 with projections 99, 30 which projections are of different number

and arrangement from the ratchet teeth 78, but bear a distinct and permanent relation thereto. When the ratchet disk 76 has been set by the receipt of the setting impulses through the magnet 82, the magnet 94 may 70 be operated, only the pole pieces of such magnet being shown, which thereupon attracts its armature 95. The attraction of this armature 95 may in any preferred or desired manner couple the constantly rotating shaft 98 with the shaft 77 or the disk 76 to drive it in a counter-clockwise direction toward its normal position. The attraction of this armature 95 has also moved the contact device comprising the springs 96, 97 75 80 carried thereon into such position that the projections 99 in the return movement of the register disk will come in contact with the spring 96 and force it into contact with the spring 97 once for each tooth 99 that 85 passes thereunder. It will therefore be seen that the operation of the register disk to any desired or predetermined set position by current impulses passing through the magnet 82 will result, when the magnet 94 is energized, in a distinct and predetermined number of circuit closures between contacts 96 and 97. It will therefore be further apparent that a register sender of the form shown in Fig. 7 is particularly adapted for 90 controlling the operation of automatic switching apparatus of the form in which impulses are sent from the sender to the automatic switching apparatus to drive the same into the desired position, and furthermore that such form of register sender is particularly adapted for use in systems where the impulses received from what may be called the primary controller, must be translated before they are transmitted to 105 the automatic switching apparatus which they are designed to control.

Primary controller.—The primary controller forming a part of the system embodying my invention shown herein and 110 which is located at the subscriber's station upon a calling line, may be of any desired structure or arrangement which will perform the desired functions. The preferred form, however, which form is well known to 115 the art and will therefore not be described in detail, comprises a switch 171, a switch 172, a switch 173, and a resistance 174. The switch 171 in its normal position closes through the contact devices 175 and 176 the 120 circuit of the line conductor 106 of the calling line. In its operated position, however, the switch 171 closes that portion of the line conductor 106 leading to the subscriber's sub-station apparatus directly to ground 125 through the contact device 175, but closes that portion of the line conductor leading to the central station to ground through the contact device 176, the switch 172 and either the resistance 174 or the switch 173. In 130

- this ground connection the switch 172 is adapted to entirely open the circuit, and the switch 173 is adapted to open and close a shunt around the resistance 174. This primary controller comprises in addition to the parts just described a plurality of well-known digits dials, each of which is adapted to be manually set to indicate, when taken together, the designation of the desired line.
- 10 When the subscriber has indicated upon these dials the designation of the line with which connection is desired, he will then operate a power lever, the first movement of which will operate the switch 171 to 15 open the connection between the two portions of the line conductor 106, and close connection from the portion of this conductor leading to the central office to ground through the switch 172 and further movement thereof will supply power for the operation of the various digits dials in their movement to their normal position. Each 20 of these dials in their return to their normal position, in which movement the dials will move one after another, will close the switch 173 according to the number to which the dial was set and then open once the switch 172. That is to say, if the first dial is set to the number 5 it will close, in its 25 return movement, the switch 173 six times, and having done so will open the switch 172 once. Assuming that the next dial was set to the number 1, it will then operate and close the switch 173 twice, and having done 30 so will open the switch 172 once, and so forth. When each of the dials has been restored to normal and in its restoration to normal operated the switches 172 and 173 as required, the switch 171 will be again 35 closed and the operation of the primary controller will be completed. The detailed operation of this primary controller so far as is necessary for an understanding of my invention will further appear in the general 40 description of the operation of the system of which it forms a part.
- Selector mechanism.* — With particular reference to the selector mechanism as shown in Fig. 4, it comprises a switch carriage or brush carrying member of the rotary type, the frame 21 of which is mounted upon a central standard or shaft 22. At the outer end of the frame a number of sets of contact brushes 23, 24, 25 are pivotally mounted 45 upon but insulated from a rod 26, and from each other, in position to sweep over sets of line terminals 27, 28, 29. The brushes have inwardly extending arms 30, bearing against which, one for each brush, are springs 31.
- 50 Latches 32, one for each set of three brushes, are pivotally mounted upon a rod 33 and arranged normally to hold the brushes from being rocked outwardly into line with the stationary terminals. Bearing against the 55 inner ends of the latches are springs 34

which hold the latches firmly against a stop rod 36. This stop rod 36 serves to prevent the latches from being moved forward too far after the brushes have been released. A stop bar 35 serves to limit the outward movement of the brushes when the latches are withdrawn. The latches 32 and stop bar 35 are of insulating material so that the circuits connected with the brushes will not be crossed thereby. The springs 31 make 60 electrical connection with the brushes; they are of sheet metal and form the teeth of combs which connect corresponding brushes in the several sets in multiple. Suitable wire clip terminals 37, 38 and 39 are provided for the circuit connections to the 65 springs and brushes.

As the brush carriage is rotated to cause the brushes to sweep over the fixed terminals, the latches first pass by a tripping device or brush selector, by which any desired set of brushes may be released and caused to swing outwardly. This tripping device comprises a shaft 40 provided with radially extending fingers 41 arranged spirally about the surface of the shaft. This shaft is adapted by mechanism, to be presently described, to be rotated so as to bring the fingers one after another into the line of travel of the several latches on the brush carriage. Only one set of brushes is intended to be released in a given operation. The shaft 40, therefore, is first rotated to bring a particular finger into position to engage the latch in the same level therewith and 70 then the brush carriage is rotated. In passing, the outward edge of this latch strikes the end of the finger, allowing one set of three brushes to be released. Continued movement of the brush carriage brings the 75 selected set of brushes into engagement with the rows of stationary terminals in the same level therewith, these brushes trailing over the terminals and making contact therewith in passing. The brush carriage is finally 80 caused to stop with the selected brushes in contact with some one set of stationary terminals. The other brushes, not being released, are held out of contact with the terminals over which they pass. A further 85 movement of the brush carriage in the same direction of rotation will carry the brushes over a restoring roller 69, which may be pivoted to the frame and which engages the free ends of the released set, causing them 90 to be pushed back into their normal latched position. After making a full revolution, the brush carriage is brought to rest in its 95 normal position again.

In the normal position of the brush carriage, as shown in Fig. 4, a pair of levers 42, 48 engage at their free ends a normal stop plate 46. At the end of the lever 42 is a roller 71 which lies in a recess of plate 46, and at the end of lever 48 is a right angle 100

extension arm 72 which makes electrical contact with said plate 46. A coil spring 54, acting upon an inwardly extending arm 44, serves to press the roller 71 with considerable force against plate 46 and thereby holds the brush carriage securely in its normal position. A flat spring 52 engages an inwardly extending arm 45 of the lever 43 and serves to press this lever outwardly but with less force than that of the coil spring 54. The spring 52 also makes electrical contact with lever 43; it is secured to but insulated from the shaft 22 of the brush carriage and terminates in a wire clip 53.

15 As the brush carriage is moved to carry the brushes over the stationary terminals, the roller 71 and the extension arm 72 engage the teeth of a cam plate 50. The roller 71 rides over the teeth while the 20 brushes are passing between terminals and drops into a notch as any released set of brushes is centrally located in a direct contact with a set of terminals. The extension arm 72 follows behind the roller one tooth 25 or notch and likewise engages a tooth as the brushes are passing between successive terminals. It passes through the space between teeth, however, without touching the plate 50, as the released set of brushes is centrally 30 located in contact with the terminals. The stop bar 35 engages the inwardly extending arm 45 just as it does the arms 30 of the brushes and thus prevents the extension arm 72 of the lever 43 from touching the bottom 35 of the notches between the teeth of plate 50, but permitting said arm 72 to touch and make contact with the top of the teeth. The teeth and notches of plate 50 are so spaced and arranged with respect to the contact 40 lever 43 that the extension arm 72 will not break contact with a tooth of plate 50 until after the brushes make contact with the stationary terminals and the roller 71 is ready to drop into a notch. The circuit arrangement, as will presently appear, is such that the motive power for driving the brush carriage cannot be cut off until the contact is thus broken between lever 43 and plate 50 and therefore not until the brushes are in 45 position to make good contact with the stationary terminals. The brush selector is also provided with an interrupter or make and break contact device comprising an arm 56 pivoted to the frame 57, engaging at 50 its free end a toothed wheel or cam 58 which rotates with the shaft or spindle 40. This arm is adapted in the rotation of the shaft to engage with the contact 59, which contact may be of the ordinary spring character, the free end only of which is shown in 55 the drawing. In the normal position of the shaft 40, the arm 56 lies in a notch of the disk 58 so that the arm 56 is out of contact with the spring contact 59, as clearly shown 60 upon the drawing. When the shaft is away

from its normal position, the arm 56 makes intermittent contact with the spring contact 59, this contact being made when the arm 56 is shifted by each tooth on the cam 58. There are as many teeth on the cam as there 70 are fingers 41 on the shaft 40 and therefore as many as there are sets of brushes, each space between two teeth upon the cam 58 corresponding to one of the fingers 41 and its coöperating set of brushes. When, therefore, the arm 56 rests in the space between any two teeth on the cam 58, a certain one of the fingers 41 is in operative position to release its coöperating set of brushes, as will be clearly understood from an inspection of 75 the drawing.

The motor mechanism for causing the rotation of the brush carriage comprises an annular iron friction disk 61 flexibly mounted at the lower end of the shaft 22, an electromagnet 62 which may be affixed in any suitable manner to the frame and a constantly rotating shaft 63 carrying an iron driving roller 64. The disk 61, roller 64, and that part of the shaft 63 which extends 80 through the center of the electromagnet 62 form the magnetic circuit of the electromagnet 62. When, therefore, current is passed through the winding of this magnet, the roller 64 attracts the disk 61 and causes 85 the latter to rotate by frictional contact therewith. The power shaft 63 is extended as shown in the drawing to carry a flexibly mounted driving disk 70 which is adapted to engage a roller 67 carried by the spindle 90 40. An electromagnet 68 controls the engagement of the disk 70 and the roller 67 in the same manner that the electromagnet 62 controls the engagement of disk 61 and roller 64. These devices are in fact electromagnetic clutches, one to cause the movement of the brush carriage and the other to cause the movement of the brush selector.

The complete selector switch mechanism is not shown in the drawing, but the elements 110 thereof appear in their proper relation to one another so as to make clear the manner in which the mechanism operates to interconnect lines. There may be as many sets of brushes and stationary terminals as desired. For example, the switch mechanism shown herein being a hundred point selector, may and preferably will have as a whole ten sets of three brushes each and one hundred sets of fixed terminals arranged in ten 115 levels of ten sets each. For simplicity, in the diagram there are only shown two sets of brushes—the eighth and ninth counting from the top down, and six sets of stationary terminals in two levels corresponding to the 120 two sets of brushes shown. It will be obvious that the number and arrangement of brushes and terminals may be changed or modified as may be required in any particular installation.

The arrangement and construction of the various portions of the system involving my invention will more fully appear in the description of the operation thereof.

5 *General description and operation.*—Assuming first that the subscriber whose station is shown to the left of Fig. 1 desires connection with some other line of the system, for example, line numbered 5149, the 10 first act of the subscriber will be the removal of the receiver from the receiver switch hook 151 of his substation apparatus 152. A circuit is now established from the battery 101 through the subscriber's line relay 102, contact 103 of the cutoff relay 104, line conductor 105, the substation apparatus and the now closed switch hook 151, line conductor 106, contacts 175 and 176, armature 107, and its back contact of the tone relay 20 108, ground relay 109 to ground and back to battery. This circuit, by the energization of the relays 102 and 109, places battery, through the front contact of the relay 102, upon the test wire 110 individual to the calling line, and ground, through the front contact of the relay 109, upon the local wire 111 individual to the group of primary line finders, in which group of finders the terminals of the calling line appear.

25 30 Immediately that a ground is placed upon the local wire 111 a circuit is completed from battery through the primary finder line relay 251, sequence switch contact 203 of the primary finder sequence switch 201, local wire 111, front contact and armature of the relay 109 to a ground and back to battery. A circuit similar to this circuit will be closed in every one of the idle primary line finders of this particular group. Since, however,

35 40 the subsequent operations of all these line finders will be the same until one of the line finders seizes the calling line, the description to that point will be only of the operation of the line finder which does actually 45 seize the calling line.

Upon the energization of the primary finder line relay 251, a circuit will be established from battery through the armature 252 and its front contact of the line relay 251, armature 253 and its back contact of the primary intermediate relay 261, sequence switch contact 204, left winding of the primary hunting relay 255 to ground and back to battery. The closure of this 50 circuit energizes the relay 255 which attracts its armatures. A substitute circuit is now closed for the energization of this relay 255, such circuit being traced from battery through the armature 252 and its front contact of the relay 251, right winding of the 55 relay 255, front contact and armature 256 of such relay and conductor 257, to the test brush 258 of this primary line finder. So long as the brushes of this finder are in contact with the terminals of an idle or non-

calling line, this circuit will be completed to ground and back to battery either through the armature 112 and its back contact of the relay 102, through the armature 114 and its front contact of the relay 108, the operation 70 of which will be hereinafter described, or through the test brush of some already connected primary finder. That is to say, the hunting relay 255 will be maintained energized by this circuit so long as the line relay 102 is not energized and the test brush 258 rests upon the test conductor of an idle or non-calling line. It should be further noted that the test brush 258 of the line finder is made in extended or elongated 80 form, so that when passing from one test terminal to the next, contact is made by it with each test terminal before it is broken with the preceding one. The energization of the relay 255 has also closed a circuit for 85 the finder rotating magnet 259 and the finder holding magnet 260 which may be traced from battery through such rotating and holding magnets in parallel, left winding of the primary intermediate relay 261, 90 sequence switch contact 205, front contact and armature 262 of the relay 255, to ground and back to battery. This circuit moreover energizes the intermediate relay 261 which attracts its armatures and thereupon 95 opens at the back contact of its armature 263 the original energizing circuit through the left winding of the relay 255. It will be noted that now the energization of the hunting relay 255 depends wholly upon the fact 100 that the test brush 258 of this finder rests on the test terminal of an idle or non-calling line.

Before proceeding further it will be noted that the intermediate relay 261, by its energization, has closed for itself a second or locking circuit which may be traced from battery through the armature 252 and its front contact of the relay 251, armature 253 and its front contact of the relay 261, 110 through the right winding of such relay, sequence switch contact 206 to ground and back to battery.

The finder rotating magnet 259 and the finder holding magnet 260 being energized, 115 the rotation of the brushes 263, 264, 258 will begin, such brushes passing over the terminals of the various lines terminating in this particular group of line finders. The brushes 263 and 264 passing over the terminals of idle or non-calling lines will in no way disturb the electrical character or condition of such lines since the conductors 265 and 266 connected to such brushes are not connected to either ground or battery at any 125 points at this stage of the operation of the primary line finder apparatus. It will therefore be apparent that the movement of the line finder over busy lines will in no way disturb or affect any conversation which 130

may be taking place over such lines. When, however, the test brush 258 reaches the test terminal of a calling line upon which, as has been heretofore described, battery is now connected, the hunting relay 255 will no longer be energized and will thereupon retract its armatures. The circuit of the finder rotating magnet 259 and finder holding magnet 260 of this intermediate line finder will therefore be immediately opened at the front contact of the armature 262 of the relay 255, and the movement of the brushes of this finder will thereupon cease with such brushes in contact with the terminals of the calling line.

At the same time that the relay 255 by its deenergization opened the circuit of the finder rotating magnet 259, it closed a circuit, including the primary selecting relay 267, from battery 113 through the front contact and armature 112 of the subscriber's line relay 102, right winding of the cutoff relay 104, back contact and armature 114 of the tone relay 108, test conductor 110, test brush 258 of the primary finder, armature 256 and its back contact of the relay 255, sequence switch contact 207, winding of the selecting relay 267, sequence switch contact 208, armature 268 and front contact of the relay 251 to ground and back to battery. If this primary finder is the only one which at this time has its brushes in contact with the terminals of the particular line, which we have assumed to be calling, the relay 267 will be energized. If, however, any other primary finder should at this time have its brushes connected to the terminals of this particular line, the selecting relays 267 of the two finders will be connected in parallel and insufficient current will be supplied from the battery 113 to energize either one of these selecting relays. We will assume, however, at present that but one line finder is now connected to the terminals of this line and will defer until later the consideration of the operations which will follow the attempted simultaneous seizure of the line by two primary finders. The selecting relay 267 will thereupon attract its armature.

At the same time that the circuit was established for the selecting relay 267 by the armature 256 of the now deenergized relay 255, a circuit was established by the retraction of the armature 262 of such relay 255 for the primary sequence switch 201, which circuit may be traced from battery through the primary line finder sequence switch 201, sequence switch contact 209, front contact and armature 270 of the relay 261, back contact and armature 262 of the relay 255 to ground and back to battery. The primary finder sequence switch 201 will now move and under the control of its special contact 202 will continue to move until it reaches the sixth position. While the primary

finder sequence switch is passing through its second to fifth positions it maintains through the sequence switch contacts 208 and 207 the circuit for the selecting relay 267 which has been above described. This not only maintains the selecting relay energized to prevent the closure of a circuit through its back contact for purposes which will be hereinafter described, but also maintains a ground upon the test brush 258 and therethrough upon the test conductor of the calling line which renders this line idle or non-calling to all of the other primary line finders in which it appears.

The primary finder sequence switch in passing out of its first position opens the sequence switch contact 209, breaking the original energizing circuit of the sequence switch itself and opens at the sequence switch contacts 204 and 205 the original energizing circuits of the relay 255 and the relay 261 respectively. The sequence switch in this movement has also opened the sequence switch contact 210 and in its third and fourth positions closed the sequence switch contact 211. The operation of these sequence switch contacts 210 and 211 is without effect in the present case and they need not at this time be considered. The sequence switch, however, in moving out of its fourth position has opened at the sequence switch contact 206 the locking circuit through the right winding of the relay 261 and this relay is thereupon deenergized. The sequence switch furthermore on coming into its fifth position closes the sequence switch contact 212. This places through the resistance 285 a ground upon the test terminal of the calling line independent of the sequence switch contacts 207 and 208 and maintains the test terminal of this line so that it will test busy or non-calling to the brushes of the other primary line finders in which this line appears. As the sequence switch leaves its fifth position it opens the sequence switch contacts 207 and 208, but since the sequence switch contact 212 has already been closed and the sequence switch contact 211 has already been opened, the opening of these sequence switch contacts and the consequent deenergization of the relay 267 is without effect.

Upon coming into its sixth position the primary finder sequence switch closes the sequence switch contacts 213, 214, 215, 216, 217, 218 and 219. The closure of the sequence switch contacts 216 and 217 has closed a circuit from battery through the sequence switch contact 216, sequence switch contact 217, supervisory line relay 272, line conductor 266, brush 264, line conductor 105, substation apparatus 152, line conductor 106, switch 171, line conductor 106, back contact and armature 107 of the tone relay 108, ground relay 109 to ground and back

to battery. This circuit energizes the supervisory line relay 272 and causes it to attract its armature, thereby closing for itself a locking circuit from battery through the sequence switch contact 215, the armature and its front contact of the supervisory line relay 272, the winding of such relay and thence as in the circuit just before described. This relay will hereafter therefore, that is, from the sixth to the eighteenth positions of the primary finder sequence switch, be under the control of the subscriber's switch hook for purposes to be hereinafter described.

Upon the closure of the sequence switch contact 213 a ground was put upon the local wire 241 leading to each of the register senders or secondary controlling organizations associated with the primary line finders of the group to which the one we have herebefore considered belongs. A circuit will be established thereupon to each of the idle secondary controllers which may be traced through one of them as follows:—from battery through secondary controller sequence switch contact 503, secondary controller line relay 551, local wire 241, primary finder sequence switch contact 213 to ground and back to battery. This circuit will energize the relay 551 which will attract its armatures and close from battery through its armature 537 and its front contact a circuit through the armature 553 and the back contact of the secondary controller intermediate relay 552, right winding of the secondary controller hunting relay 555, to ground and back to battery. The relay 555 will thereupon be energized and close a circuit from battery through the secondary controller finder rotary magnet 559 and finder holding magnet 560 in parallel, right-hand winding of the relay 552, front contact and armature 557 of the relay 555, to ground and back to battery. This will start the finder brushes of the secondary controller rotating, hunting for the terminals associated with the particular primary finder which has been taken for use. It should be noted, however, that immediately upon the energization of the relay 555 the test brush 543 of the secondary controller line finder has been connected through the armature 556 and its front contact of the relay 555, left winding of such relay and the armature 537 and front contact of the relay 551 to battery. Since therefore this finder brush 543 like the test brush in the primary line finder hereinbefore described is so arranged as to make contact with one of the test terminals before breaking it with the preceding one it will be continuously connected to ground through the primary finder sequence switch contacts 206 of the idle or non-calling primary finders. Furthermore this finder brush in passing over terminals of primary finders, which are at this time connected to other

secondary controllers than the particular one with which we are concerned, will find a ground through the secondary controller test relay 558 of such secondary controller. It will be seen therefore that until the brushes of the secondary controller line finder come in contact with the primary finder which is actually "calling", the test brush 543 will always be upon a circuit connected to ground and the hunting relay 555 will therefore be maintained energized. When, however, the test brush 543 rests upon the test terminal of a "calling" primary finder it will find battery upon such terminal and the relay 555 will be deenergized, it being noted that the secondary controller intermediate relay 552 by the energization of the circuit above noted through its right-hand winding has opened the original energizing circuit for the hunting relay 555 and has closed for itself a locking circuit from battery through the armature 537 and its front contact of the secondary controller line relay 551, armature 553 and its front contact of the relay 552, left winding of such relay to ground and back to battery. This deenergization of the relay 555 has opened at the front contact of its armature 557 the circuit of the secondary controller finder rotating and holding magnets and this finder stops with its brushes 541, 542 and 543 in contact with the terminals 273, 274 and 275 of the "calling" primary finder. At the same time the deenergization of the hunting relay 555 closes two circuits, one for the secondary controller sequence switch 501 and the other for the secondary controller test relay 558. The circuit for the test relay 558 extends from battery at the "calling" primary finder through primary sequence switch contact 214, right winding of relay 261, to the test terminal 275, test brush 543 of the secondary controller line finder, armature 556 and its back contact of the relay 555 through the test relay 558, front contact and armature 538 of the relay 551 to ground and back to battery. If at this time the brushes of but one secondary controller rest upon the terminals associated with this particular primary finder, the test relay 558 will be operated. If on the other hand, the brushes of more than one secondary controller rest upon the terminals associated with this particular primary finder, the current will be so divided between them that none of the test relays 558 will operate. Assuming, however, for the time being that the brushes of but a single secondary controller are now upon the terminals of this primary finder, the relay 558 will be energized and attract its armature. The closure of the circuit through this relay 558 has also caused the energization of the intermediate relay 261 of the primary finder since it will be remembered that the battery which has served to energize the relay 558

was supplied through the primary finder sequence switch contact 214 and the right winding of the relay 261. The energization of this relay 261 is without effect, however, at the present time.

The circuit closed by the deenergization of the relay 555 for the secondary controller sequence switch may be traced as follows: battery, through the secondary controller sequence switch 501, sequence switch contact 504, armature 554, and front contact of the relay 552, back contact and armature 557 of the relay 555 to ground and back to battery. The secondary controller sequence switch will now move from its first position, and under the control of its special contact 502 will come to rest only when it reaches its sixth position. In this movement the sequence switch has opened the contact 503, but before opening such contact has closed the sequence switch contact 506, in this manner substituting for the circuit of the test relay 558 the ground connected to its own armature in place of the ground connected to the armature 538 of the relay 551. It will be noted that from this time on until the sixteenth position of the secondary controller sequence switch is passed, the test relay 558 will be maintained energized so long as battery is supplied thereto over the test brush 543. The line relay 551 being now deenergized by the opening of the sequence switch contact 503 has opened the locking circuit through the left winding of the intermediate relay 552 and such relay will also be deenergized.

While the sequence switch 501 is moving through its fourth and fifth positions a circuit is temporarily closed extending from battery through the primary finder sequence switch contact 216, selecting relay 267, sequence switch contact 218, terminal 274, secondary controller finder brush 542, secondary controller sequence switch contact 509, front contact and armature of the relay 558 to ground and back to battery. This temporary circuit energizes the selecting relay 267 which attracts its armature and closes a circuit for the primary finder sequence switch driving it under the control of its special contact 202, from its sixth position into its eighth position. The circuit may be traced from battery through the primary finder sequence switch 201, sequence switch contact 219, front contact and armature of the selecting relay 267 to ground and back to battery.

The primary finder sequence switch in passing out of its sixth position has opened the sequence switch contact 213, thereby opening the circuit for the secondary controller line relays of all of the "unsuccessful" secondary controllers, which thereupon cease their movement. It will be remembered that the line finders of all of the idle

secondary controllers of this group began to move upon the closure of the primary finder sequence switch contact 213, and that with the exception of the secondary controller line finder which has seized the terminals of the "calling" primary finder, the idle secondary controllers of this group have continued in their movement. When, however, the primary finder sequence switch contact 213 opens, the line finders of all such idle secondary controllers will stop and await the subsequent closing of the primary finder sequence switch contact 213 of this particular primary finder, or of some other primary finder of the group with which they are associated. The primary finder sequence switch in moving into its seventh and eighth positions has, by means of the sequence switch contacts 212, 220 and 221, cut out the resistance 285 between the test brush 258 of the primary line finder and ground, so that in the seventh and eighth positions and thereafter until the sixteenth position is passed, it is connected directly to ground first through the sequence switch contact 221 and then through the sequence switch contact 220, the circuit through the sequence switch contact 221 being closed before the sequence switch contact 212 is opened. The circuit through the right winding of the cut-off relay 104 (see Fig 1) being now connected directly to earth without either the resistance of the relay 267 or the resistance 285, sufficient current will pass to energize the cut-off relay 104, which thereupon attracts its armatures closing by its armature 115 and the front contact thereof a shunt including resistance 118 around the front contact and armature 114 of the relay 108, and also by its armature 103 opening the circuit between the subscriber's line relay 102 and the line conductor 105, at the same time providing a substitute path to ground for said subscriber's line relay and thereby maintaining it energized through such armature 103, its front contact and the resistance 121. It should be noted at this point that current is now supplied to the ground relay 109 from battery through the sequence switch contact 215, supervisory line relay 272, line conductor 266, line conductor 105, substation apparatus 152 and line conductor 106.

The primary finder sequence switch being now in its eighth position and the secondary controller sequence switch being now in its sixth position, the apparatus is ready for the operation of the primary controller apparatus 170 located at the subscriber's station, the controlling circuit being closed up to the front contact of the armature 107 of the tone relay 108 as follows: battery, secondary controller sequence switch 511, register switching relay 528, register operating relay 527, resistance 526, back contact and ar-

mature 596 of the units transfer relay 594, secondary controller line finder brush 541, terminal 273 of the primary finder, resistance 276, primary finder sequence switch 5 contact 222, conductor 265, primary line finder brush 263 and line conductor 106.

It may here be noted that the instructions given the subscriber at the substation, for the proper operation of the system, indicate

- 10 that he should first remove his receiver from its switch hook and then proceed to set the sending or primary controller mechanism to the designation of the line desired, in this case, as has been heretofore assumed.
- 15 5149. If the subscriber has followed these instructions, the primary line finder and the secondary controller will have associated themselves with his line before the sending operation of the primary controller begins.
- 20 To accomplish this the movement of the finder brushes in the respective line finds and their associated sequence switches are adapted to be accomplished, if necessary, at high speed without loss in accuracy and precision.
- 25 If, however, for any reason, either through the neglect of instructions by the subscriber or by the holding up of any of the operations of the primary finder or secondary controller, the operation of the
- 30 primary controller should begin before the primary finder and secondary controller become associated with the subscriber's line, certain operations take place to prevent confusion, which operations will be hereinafter referred to. It will be assumed for the present that the primary finder and the secondary controller have become associated with the calling line before the switches of the primary controller, indicated at 171, 172
- 35 and 173, begin their operations.

When now the switch 171 is operated a ground will be placed upon the back contact 175 thereof before the circuit is opened by the movement of the movable member 176 of such switch and its closure with the front contact thereof. This ground on the back contact 175 of this switch maintains the energizing circuit of the supervisory line relay 272, which circuit therefore continues to depend upon the closed condition of the subscriber's switch hook. The operation of the switch 171 of the primary controller has, however, caused the deenergization of the ground relay 109, which thereupon retracts its armature and completes a circuit for the tone relay 108, such circuit being traced from battery through the front contact and armature of the subscriber's line relay 102, relay 108, back contact and armature of the relay 109 to ground and back to battery. The tone relay is thereupon energized and in attracting its armature 107 extends the controlling circuit, heretofore traced to the front contact thereof, through such armature 107, line conductor 106, movable mem-

ber 176 of the switch 171 of the primary controller, front contact thereof, switch 172, resistance 174 to ground and back to battery.

It may be noted that at this time, as will be hereinafter pointed out, the movement of all unsuccessful line finders will cease due to the deenergization of the ground relay 109 as just described, provided, of course, that there are no other calling lines in this group which as yet no primary finder has successfully seized. Of course, if a ground is maintained on the local wire 111 at this time by an energized ground relay of some other calling line of this group, the "unsuccessful" primary line finders will not stop, but if this is the only line "calling" at this time, the movement of these "unsuccessful" primary line finders which has been maintained up to this time will now cease.

As hereinbefore stated, the subscriber's primary controller may be as desired of any construction and arrangement well known to the art, in which dials or equivalent devices are provided which may be so set or adjusted as to indicate the designation of the desired line, and which, after having been set or adjusted, may be caused to operate that they will one after another close the switch 173 a number of times corresponding to the number designated upon such dial, and before the operation of the next succeeding dial once open the switch 172. In the preferred form, after the dials have been set or adjusted to indicate the designation of the desired line, their operation is started and controlled by the movement of a lever, in the movement of which lever the switch 171 is operated, such switch 171 remaining operated until the completion of the operation of all of the dials or equivalent devices of the primary controller.

The dials of the primary controller having been set to indicate the designation of the desired line, in the case assumed, 5149, and the switch 171 operated, the circuit, heretofore traced through the primary controller and the relays 527 and 528, is completed through the resistance 174. This will cause the energization of the switching relay 528, but the register setting relay 527 will not be operated owing to the inclusion of the resistance 174. When, however, the first or thousands dial in its operation closes the switch 173, thereby shunting the resistance 174, the register setting relay 527 will be energized attracting its armature and closing the following circuit:—from battery through the thousands registering magnet 562, back contact and armature 566 of the thousands transfer relay 564, front contact and armature of the registering setting relay 527 to ground and back to battery. The closure of this circuit causes the thousands register magnet to be ener-

gized and to operate the pawl associated therewith to drive the disk of the thousands register 561 clockwise one step from its normal position. When the switch 173 is again opened at the primary controller the register setting relay 527 will be again deenergized and by the opening of the circuit, heretofore traced, the thousands register magnet will also be deenergized, and will thereupon be ready upon a second closure of its energizing circuit to control its associated pawl in such a manner as to move the disk of the thousands register 561 a second step. It will be noted, however, that the disk of this thousands register 561 in its first step has opened the contacts 568 and closed the contacts 563. This has prepared a circuit which may be traced from battery through the contacts 563, left winding of the thousands transfer relay 564, sequence switch contacts 505 to the back contact of the switching relay 528, which relay, however, it will be remembered, is now maintained energized.

25 In the case assumed the thousands digit of the designation of the desired line was 5. The switch 173 will therefore be operated six times by the thousands dial of the primary controller, and, through the operation of the register setting relay 527 six times in response to the closure of this switch 173, the thousands register magnet has moved the register disk of the thousands register six steps. At this time the switch 172 of the primary controller will be operated once. This by opening the circuit entirely will cause the deenergization of the switching relay 528 and the circuit, heretofore traced through the left winding of the thousands transfer relay 564, will be completed, energizing such thousands transfer relay 564. This thousands transfer relay by the attraction of its armatures has closed for itself a locking circuit from battery through the right-hand winding of such relay, front contact and armature 565 of such relay, sequence switch contact 507 to ground and back to battery. The primary function, however, of this relay was to transfer the control of the register setting relay 527 from the thousands register magnet to the hundreds register magnet, and it did this by the attraction of its armature 566, so that now a circuit may be traced from battery through the hundreds register magnet 572, back contact and armature 576 of the hundreds transfer relay 574, front contact and armature 566 of the thousands transfer relay 564 to the front contact of the register setting relay 527. Before the hundreds dial or equivalent device begins to move in the primary controller the switch 172 is again closed, energizing the switching relay 528 and opening the original circuit to the thousands transfer relay 564. The hundreds

dial in its movement, since it was set to designate the figure 1, will close the switch 173 twice and then open the switch 172 once.

It may here be noted that in the operation of each of the dials, if it is set to the "0" digit, it will close the switch 173 once in its operation in returning to normal; if it is set at "1" it will operate the switch 173 twice; if it is set at "2" it will operate the switch 173 three times, etc.; that is to say that if the thousands dial, for example, is set at the figure 0 it means that the line desired is located in the first thousands group of lines at the exchange and therefore a single impulse will be sent by closing the switch 173 in order to select at the proper time the first thousands group of lines at the exchange. The operation of the hundreds dial therefore has caused the register setting relay 527 to pull up and release twice, thereby closing through its armature to ground the circuit which has been heretofore traced from the hundreds register magnet 572, which circuit has energized such magnet to cause the disk of the hundreds register 571 to advance clockwise two steps from its normal position. As soon as the hundreds register left its normal position the contacts 573 were opened and the contacts 573 were closed, preparing a circuit from battery through the contacts 573, left winding of the hundreds transfer relay 574, sequence switch contact 505, and back contact of the switching relay 528. When now the switch 172 is opened once by the movement of the hundreds dial, the switching relay 528 will be deenergized and in retracting its armature complete the circuit through the left winding of the hundreds transfer relay 574, which has just been traced. This will cause the energization of the relay 574 which closes a locking circuit for itself through its armature 575 and its front contact and the sequence switch contact 507 similar to the locking circuit of the thousands transfer relay, and also shifts the control circuit of the register setting relay from the hundreds register magnet 572 to the tens register magnet 582, and such circuit may now be traced as follows:—From battery through the tens register magnet 582, back contact and armature 586 of the tens transfer relay 584, front contact and armature 576 of the hundreds transfer relay, front contact and armature 566 of the thousands transfer relay, and front contact of the register sending relay 527.

The operation of the tens dial will now control the movement of the register disk of the tens register 581 in the manner now well understood causing it to move five steps from normal in response to the five closures of the switch 173, thereby opening the contacts 588 and closing the contacts 583.

and preparing the energizing circuit through the left winding of the tens transfer relay 584 precisely as has been before described in connection with the hundreds register and 5 the hundreds transfer relay. Again, as before the single opening of the switch 172 by the tens dial will cause the energization of the tens transfer relay which will lock itself up and shift a circuit from the tens register 10 to the units register precisely as has been heretofore described in connection with the thousands and hundreds registers.

The operation of the units dial will in a precisely analogous manner cause the units 15 register to move ten steps from normal in response to the ten closures of the switch 173 by the units dial. The circuit of the units register magnet during this operation may be traced as follows:—From battery through 20 the units register magnet 592, front contact and armature 586 of the tens transfer relay, front contact and armature 576 of the hundreds transfer relay, front contact and armature 566 of the thousands transfer relay and 25 front contact and armature of the register setting relay 527 to ground and back to battery. In this case too, of course, the contacts 598 have been opened and the contacts 593 have been closed preparing as before a circuit through the left-hand winding 30 of the units transfer relay 594, which is closed upon the opening of the switch 172 by the units dial, and the consequent de-energization of the switching relay 528. At 35 this time the switch 171 is returned to its normal condition, and the apparatus individual to the calling line is now ready for conversation. It will be noted that when the switch 171 returned to its normal condition, the circuit was closed between the moving part 176 and the back contact 175 thereof before the ground was removed from such back contact, in this way maintaining the circuit of the supervisory line relay 272, the 40 circuit of which now extends through the subscriber's substation apparatus as heretofore described, thence through the switch 171, line conductor 106, armature 107 and its front contact of the tone relay 108, line conductor 106, primary finder brush 263, conductor 265, primary sequence switch contact 222, resistance 276, terminal 273, secondary controller finder brush 541, armature 596 and its front contact of the units transfer 45 relay 594 to ground and back to battery. It will be noted that this circuit will be maintained until the primary finder sequence switch moves from its thirteenth position, that is to say, so long as the secondary controller is operatively associated with the primary finder. It may also be noted that before the primary finder sequence switch leaves its thirteenth position, a substitute circuit is closed from the line conductor 265 through resistance 288, sequence switch con- 50

tact 224, back contact and armature 262 of the relay 255 to ground, which furnishes ground for the circuit just described during the thirteenth and fourteenth positions of the sequence switch. When the sequence 55 switch reaches its fourteenth position another circuit is completed to ground from the conductor 265, this one being through the sequence switch 223 and the retardation coil 277. This circuit will be maintained 60 subject to the restoration of the subscriber's receiver upon the switch hook until the apparatus is to be restored, ground having been maintained constantly upon the conductor 265 between positions thirteen and 65 fourteen of the sequence switch.

Recurring to the operation of the thousands transfer relay, which, as may be remembered, attracted its armatures to close for itself a locking circuit and also thereby 70 shifted the circuit controlled by the register setting relay 527 from the thousands register magnet to the hundreds register magnet, it will be noted that immediately this operation has taken place the control of the desired selection and the movement of the automatic switching apparatus under such control may commence.

It will also be observed, although it has not been heretofore referred to, that the thousands transfer relay when it attracted its armature 75 not only closed for itself a locking circuit through its right winding but also closed a circuit from battery through the secondary controller sequence switch 501, sequence switch contact 520, front contact and armature 565 of the relay 564, sequence switch contact 507, to ground and back to battery. The sequence switch will thereupon move 80 from its sixth position into its tenth position, it being noted that the energizing circuit is maintained closed through the sequence switch contact 520 from the sixth to the ninth positions. This movement of the sequence switch into its tenth position closes 85 the sequence switch contacts 512 and 513, but does not in any way affect the circuits over which the hundreds, tens and units registrations are controlled. By this means the control of thousands selection may take place at 90 the same time that the hundreds, tens and units registers are being set from the substation without any confusion or inaccuracy.

The primary finder sequence switch now 95 being in its eighth position and the secondary controller sequence switch being in its tenth position, a circuit is closed from battery through the primary finder sequence switch contact 216, selecting relay 267, sequence switch contact 218, terminal 274, secondary controller finder brush 542, secondary controller sequence switch contact 510, register restoring relay 529, back contact and armature 533 of the register cutoff relay 530, sequence switch contact 512, front contact 100

and armature 565 of the thousands transfer relay 564, sequence switch contact 507 to ground and back to battery. The selecting relay 267 is thereupon energized and closes 5 at the front contact of its armature a circuit from battery through the primary finder sequence switch 201, sequence switch contact 219, front contact and armature of the relay 267 to ground and back to battery. The 10 closure of this circuit causes the primary sequence switch to move from its eighth into its ninth position, thereby closing the following circuit:—battery, thousands wet point finder rotary magnet 278, sequence switch contact 225, front contact and armature of the relay 267, to ground and back to battery. This causes the energization of the 15 thousands wet point device rotary magnet and in response thereto the thousands wet point device will begin to move. In each stage of the movement of this thousands wet point device it will operate a group of contacts each group comprising a contact associated with the local wire leading to a group 20 of thousands intermediate line finder devices and a test wire also leading to such group, such test wire being individual to this particular primary finder.

As will be readily understood, and is grammatically indicated on the right-hand side of Fig. 2, the thousands wet point device associated with the primary finder will in its first stage, after having left its normal position, prepare a battery circuit for the test wire individual to this primary finder, which may be traced from battery through the line relay 251, sequence switch contact 226 and contact member 279 to the test conductor 280. It will at the same time prepare a ground connection for the local wire leading to the first group which may be traced as follows: contact member 281 of the line relay 251, sequence switch contact 227 and contact 297 to the local wire 282. Since, however, the sequence switch is still in its ninth position these connections are still opened and will only be closed when the sequence switch on coming into its tenth position closes the sequence switch contacts 226 and 227. It will be further noted that the thousands wet point device in leaving its normal position has closed the contacts 283 and will maintain them closed until it is again in its normal position, such contacts being known as the thousands wet point off-normal switch. An important feature of this wet point device is that in passing from any one stage to the next, as for example, from its normal stage to its first stage, or from its first stage to its second stage, or in fact between any two stages thereof, it will close the interrupter contacts 284, that is to say, as soon as the thousands wet point device leaves its normal position the interrupter contacts are closed and will remain closed to ground and back to battery. The energization of the magnet 567 causes, through the operation of its cooperating pawl, the movement of the register disk of the thousands register one step toward normal, that is to say in a reverse or counter-clockwise direction. The shunting of the register restoring relay 529 by the closure of the interrupter contacts 284 causes this relay to be deenergized, thereby preparing it to step the register disk of the thousands register another step toward its normal position upon a subsequent energization. When the wet point finder reaches its first stage or position, the interrupter contacts 284 will be again opened, but the circuit of the selecting relay 267 will be maintained through the circuit including the register restoring relay 529, and in consequence this relay 529 will be again energized, in turn energizing the thousands restoring magnet 567 to cause the register disk of the thousands register to move another step toward its normal position. The relay 267 being maintained energized, the thousands wet point rotary magnet will continue energized and the wet point device will move from its first stage or position, again closing the interrupter contacts 284, maintaining the energization of the relay 267, but shunting the relay 529 as before. This alternate energization and deenergization of the register restoring relay 529 will continue until it has been energized six times. When now, for the sixth time, the register restoring relay is deenergized by the closure of the interrupter contacts 284, which will take place while the thousands wet point device is moving from

its fifth stage to its sixth stage, a circuit will be closed from battery through the contacts 568 which are now again closed, due to the six restoring impulses through the 5 restoring magnet 567; through the sequence switch contact 569, left winding of the register cut-off relay 530, back contact and armature of the register restoring relay 529 to ground and back to battery. The energization of the relay 530 closes a circuit from battery through the secondary controller sequence switch 501, front contact and armature 533 of the relay 530, sequence switch contact 512, front contact and armature 565 10 of the thousands transfer relay 564, sequence switch contacts 507 to ground and back to battery. The closure of this circuit causes the sequence switch to move from its tenth to its twelfth position under the influence 15 of the special contact 502, in which position it is ready to control hundreds selection, provided hundreds registration is completed and the hundreds transfer relay 574 is energized to provide a ground circuit through 20 the sequence switch contact 507 for the selection controlling circuit. It will, of course, be apparent that this hundreds selection cannot take place until battery is provided at the distant end of this circuit 25 through the register restoring relay 529, indicating that the apparatus is ready to take up hundreds selection. It will be further noted that the secondary controller sequence switch, in moving from its tenth to its 30 twelfth position has destroyed the energizing circuit of the relay 530 by opening the sequence switch contact 569. The closure of the sequence switch contact 579 is without effect at this time since the contacts 578 35 are now open.

Referring back now to the primary finder apparatus at the time when the interrupter contacts 284 have shunted the register restoring relay the sixth time, it will be seen 40 that the selecting relay 267 will be maintained energized until the thousands wet point device on coming into its sixth stage to close the contacts associated with the test and local lines leading to the sixth group of 45 thousands line finders has again opened the interrupter contacts. As soon as this occurs the relay 267 will be deenergized and by the retraction of its armature open the circuit of the rotary magnet, stopping the wet point 50 device in its sixth stage or position. The same movement of the armature of the relay 267 has closed a circuit from battery through the primary finder sequence switch 201 through the sequence switch contact 229, back contact and armature of the relay 267 to ground and back to battery. The primary 55 finder sequence switch will therefore immediately move from its ninth into its tenth position.

In the tenth position of the sequence

switch, the sequence switch contacts 226 and 227 are closed. This places battery upon the test conductor to the group selected by the thousands wet point device, in this instance the sixth group, from battery through the 70 relay 251, sequence switch contact 226, contacts 279 to the test conductor 280, and also places ground upon the local conductor of the sixth group from ground at the back contact device 281 of the relay 251 through 75 the sequence switch contact 227, contact devices 297 to the local conductor 282. In the tenth position of the primary finder sequence switch the sequence switch contact 208 is also closed which prepares a circuit 80 to energize the selecting relay 267 and is dependent upon the energization of the line relay 251. Furthermore the sequence switch contact 230 is also closed in this position of the sequence switch, but this is without 85 effect at this time.

It may be here noted that the selection controlling circuit, including the register restoring relay 529, is now opened and will not be again closed until the twelfth position of the primary finder sequence switch, when it will be closed to the line conductor 298 at the primary finder sequence switch contact 231.

The thousands wet point device and the 95 primary finder apparatus in coöperating to place a ground upon the local conductor of the sixth group has closed a circuit from battery through the intermediate line relays 251 of all of the idle intermediate line finders 100 of the sixth group, that is, the group of intermediate switches appropriated to the sixth thousand lines, through the intermediate finder sequence switch contact 304, sequence switch contact 303 to the local wire, 105 and thence to ground as has been before described.

Before proceeding further, attention will be called to the fact that while we have assumed that the thousands wet point device 110 has selected the sixth group, the drawings only show an intermediate finder of the first group connected to the thousands wet point device, and the description will be given as though it related to this intermediate finder 115 of the first group, it being obvious that the operation of a finder in the sixth group would be precisely similar to the operation of an intermediate finder in the first group, and that the description of the one will do 120 as well as of the other.

Upon the energization in the various intermediate finders of the selected group of the intermediate line relay 351, there is a circuit established from battery through 125 armature 352 and front contact of the relay 351, armature 355 and back contact of the intermediate relay 361, left winding of the intermediate hunting relay 355, sequence switch contact 305, to ground and back to 130

battery. As before, we will consider the circuits and operations with regard to one of the intermediate line finders, such operation being the same in all of the line finders of the selected group until one of such finders has seized upon the calling terminals, that is to say, the terminal the test conductor of which is connected to battery at this time. This circuit through the left winding of the relay 355 energizes such relay and closes for itself a substitute circuit from battery through the armature 352 and front contact of the relay 351, right winding of the relay 355, front contact and armature 356 of such relay, test brush 358 of the intermediate line finder, test conductor 280 of an idle or non-calling line, which test conductor, it will be observed by reference to Fig. 2, is connected to ground directly if it is idle, or is connected to ground through the test brush of some other intermediate finder and its intermediate test relay 386 if it is already being used. Therefore, as long as the test brush which, as before, is made of such shape or configuration as to bridge from one test contact to the next in moving from one to the other, remains upon a test terminal of an idle or non-calling primary finder, a circuit will be maintained for the relay 355 through its right-hand winding. It should be further noted that the energization of the relay 355 has closed a circuit from battery through the intermediate finder, rotating magnet 359 and the intermediate finder holding magnet 360 in parallel, the left-hand winding of the relay 361, front contact and armature 354 of the relay 355 to ground and back to battery. This causes the energization of the relay 361 which closes for itself a locking circuit from battery through the armature 352 and front contact of the relay 351, armature 353 of the relay 361, through the right winding of such relay, sequence switch contact 305 to ground and back to battery, and also causes the energization of the finder rotary magnet 359 and the finder holding magnet 360. The energization of these two magnets causes the intermediate line finder brushes 363, 364 and 358 to move. This rotation of the intermediate line finder brushes will continue until the test brush 358 reaches the test terminal of a "calling" line. When this occurs the relay 355 will be deenergized and will retract its armatures, the armature 354 opening the circuit of the intermediate finder rotary magnet and thereby stopping the movement of the brushes. This same armature closes in its retracted position a circuit from battery through the intermediate finder sequence switch 301, sequence switch contact 307, resistance 399, relay 367, sequence switch contact 306, front contact and armature 375 of the relay 361, back contact and armature 354 of the relay 355 to ground and back to battery. The closure of this circuit energizes the relay 367 which, by the attraction of its armature, closes a circuit for the intermediate sequence switch 301 through the sequence switch contacts 308 and 309 which thereupon moves out of its first position and without stopping in its second position moves until it comes into its third position where it again stops. This movement through the second position is under the control of the special contact 302. The retraction of the armature 356 of the relay 355 establishes in the first position of the sequence switch a circuit from the battery connected over the test conductor through the test brush 358 of the intermediate line finder, armature 356 and its back contact of the relay 355, intermediate test relay 386, sequence switch contact 320, armature 368 and front contact device of the relay 351 to ground and back to battery. This circuit through the intermediate test relay 386, which will be maintained in the second position of the sequence switch, has immediately placed a temporary ground upon the connected test terminal to make the same test busy. If this particular intermediate line finder is the first to make contact with the "calling" test terminal the relay 386 will be energized. If on the other hand, as has been before referred to in connection with the primary line finder, two or more intermediate finders should make contact simultaneously with the "calling" test terminal, current from the battery connected to test terminal would be so divided that none of the relays 386 would be energized. Assuming for the time being that this intermediate line finder was the first to make contact with the "calling" test terminal, the relay 386 will be energized.

As the intermediate finder sequence switch leaves its first position the locking winding of the intermediate relay 361 will be opened at the sequence switch contact 305, and this relay will be deenergized allowing its armatures to retract. As the sequence switch comes into its second position an additional earth connection is supplied to the circuit of the relay 386, which extends from the winding of such test relay through the sequence switch contact 311, front contact and armature of such relay 386 to ground. This ground will be placed upon the circuit of the intermediate test relay before the ground through the sequence switch contact 320 is removed, the energization of the relay 351 being maintained in spite of the opening of the sequence switch contact 303 by a circuit through the sequence switch contact 304 and the armature of the relay 386. This circuit is opened, however, when the sequence switch reaches its third position. The circuit of the test relay 386 having once been established through its armature and

the sequence switch contact 311 will be maintained through the seventh position of the sequence switch provided battery is maintained upon the test conductor 280. In 5 this way the relay 386 is first used as a test relay to insure the fact that only one intermediate line finder attaches itself to the "calling" terminals, but after the sequence switch has passed into its second position 10 and thereafter it operates as a disconnect relay, as will be hereinafter described, being maintained operated so long as, and only so long as, battery is supplied over the test terminals of the line to which the finder 15 is now connected.

16 The intermediate finder sequence switch in leaving its second position has opened the energizing circuit of the relay 351, which thereupon allows its armatures to retract.

17 When the sequence switch reaches its third position, a circuit is established from battery through the armature 352 and its back contact of the relay 351, relay 367, sequence switch contact 312, line conductor 365, intermediate finder brush 363, line conductor 298, primary finder sequence switch contact 231, terminal 274, secondary controller line finder brush 542, secondary controller sequence switch contact 510, register restoring 25 relay 529, back contact and armature 535 of the register cutoff relay 530, sequence switch contact 514, front contact and armature 575 of the hundreds transfer relay 574, sequence switch contact 507 to ground and back to 30 battery. This is the hundreds selection controlling circuit, and its closure has energized the intermediate selecting relay 367 and the register restoring relay 529. The energization of the relay 529 has closed a 35 circuit for the hundreds register restoring magnet 577 from battery through the restoring magnet 577, sequence switch contact 515, armature and front contact of the relay 529 to ground and back to battery. The 40 hundreds register restoring magnet will therefore energize to accomplish one step of the register disk of the hundreds register in the restoring direction.

45 Meanwhile the energization of the intermediate selecting relay 367 has closed a circuit from battery through the sequence switch 301, sequence switch contact 308, front contact and armature of the relay 367, back contact device 381 of the relay 55 351 to ground and back to battery. The intermediate sequence switch, due to the closure of this circuit, moves from its third to the fourth position, in such movement closing the sequence switch contacts 314 and 60 315, but does not in this movement disturb any of the connections established in its third position, opening only its own energizing circuit through the sequence switch contact 308. The hundreds selection controlling 65 circuit remains undisturbed.

The operation of the hundreds wet point device will now take place under the control of the hundreds register of the secondary controller. Upon the coming of the intermediate sequence switch into its fourth position a circuit was established from battery 70 through the hundreds wet point device rotary magnet 378, sequence switch contact 315, front contact and armature of the relay 367, back contact device 381 of the relay 351 to ground and back to battery. The hundreds wet point device will thereupon commence to move, and in its movement operate the interrupter contacts 384 precisely as has already been described in connection with 80 the thousands wet point device. The closure of these interrupter contacts 384 places a ground upon the hundreds selection controlling circuit between the intermediate selecting relay 367 and the register restoring 85 relay 529, thereby shunting and deenergizing the relay 529 while maintaining the relay 367 energized. The deenergization of the register restoring relay has permitted the deenergization of the hundreds register restoring magnet to prepare itself for producing a second restoring step of the hundreds register disk. Since, however, contacts 578 have not as yet been closed by the coming of the hundreds register disk into its normal 95 position the register cutoff relay 530 will not be energized at this time. When the hundreds wet point device reaches its first stage or position in which the contact devices associated with the first group of final finders, that is, the group of final finders individual to the first or zero hundreds of the system are operated, the interrupter contacts 384 are opened and the shunt therefore removed from around the register restoring 100 relay 529. This relay therefore is energized and again closes a circuit through the hundreds register restoring magnets 577 which produces a second step of the hundreds register disk toward its normal position. It 105 will be remembered by reference to the designation of the line with which we have assumed connection is desired that such line is in the second hundred of the sixth thousand of the lines connected with the exchange, and that in setting the registers to control the selection of the line desired the hundreds register was moved from normal 110 two steps. When therefore the interrupter contacts 384 are again closed while the wet point device is passing from its first stage to its second stage, the register restoring relay 529 will be deenergized closing by the retraction of its armature a circuit from battery through contacts 578, sequence switch 115 contacts 579, left winding of the register cutoff relay 530, back contact and armature of the relay 529 to ground and back to battery. The relay 530 will thereupon be energized and by the attraction of its armature 120

125 130

535 open the circuit of the register restoring relay 529 and close a circuit from battery through the secondary controller sequence switch 501, front contact and armature 535
 5 of the relay 530, sequence switch contact 514, front contact and armature 575 of the hundreds transfer relay 574, sequence switch contact 507 to ground and back to battery. The secondary controller sequence switch
 10 will thereupon, under the influence of its special contact 502, move into its fourteenth position.

When the hundreds wet point device on coming into its second stage or position
 15 opens the interrupter contacts 384, both of the energizing circuits for the intermediate selecting relay 367 will be opened since it will be remembered that the circuit of the register restoring relay 529 has been opened
 20 at the back contact of the relay 530. The relay 367 will therefore be deenergized and open at its front contact the circuit of the rotary magnet 378 of the hundreds wet point device, causing such device to stop in its
 25 second stage or position with the contacts associated with the test and local conductors leading to the second group of final line finders, individual to the selected hundred lines, in operated condition. At the same
 30 time the relay 367 has closed at its back contact a circuit from battery through the sequence switch 301, sequence switch contact 314, back contact and armature of the relay 367, back contact device 381 of the relay 351
 35 to ground and back to battery. The closure of this circuit causes the intermediate sequence switch to move from its fourth to its sixth position, thereby opening the sequence switch contact 312 located in the hundreds selection controlling circuit and also opening the sequence switch contacts 314, 315 and 325. This latter sequence switch contact 325 has been in the third and fourth positions of the sequence switch closed to prevent a moving final line finder from being interfered with by the operation of the contact devices of the groups operated by the hundreds wet point device before the selection is completed. It will be noted in this connection
 40 that when selection is completed this ground is removed and immediately thereafter, by the sequence switch coming into its sixth position, battery is substituted for this ground upon the test conductor individual to this
 45 intermediate finder leading to the selected group of final finders. This battery circuit is traced from battery through the right winding of the relay 351, sequence switch contact 316, upper and lower contact devices 379 in the selected group of contact devices to the test conductor 380. At the same time the sequence switch by the closure of the sequence switch contact 317 has connected ground to the local conductor leading to the
 55 selected group of final line finders, this

ground being connected through the back contact device 381 of the relay 351, sequence switch contact 317 and contact device 389 of the operated group to the local conductor.

By reference to the description of the operation of the primary finder apparatus and its associated thousands wet point device it will be seen that interference with moving intermediate finders was prevented while the thousands wet point device was moving 75 in a manner exactly similar to the way interference with moving final finders was prevented as just described. In the primary finder apparatus a ground was maintained upon the operated contacts 279 in the ninth 80 position of the primary sequence switch during which position the movement of the thousands wet point device took place. This ground was applied through the back contact device 281 of the relay 251 and the sequence switch contact 228, and was removed in the tenth position of the primary sequence switch.

Ground having been placed by the hundreds wet point device upon the local line 90 of the second group of intermediate line finders leading to the second group of final finders, all of the idle finders of this group will have their associated line relays 451 energized. Circuit may be traced from battery through the final line relay 451 through the final finder sequence switch contacts 404 and 403 to the local conductor 382, and thence to ground as heretofore traced. This will energize the relay 451 which attracts 100 its armatures and closes a circuit from battery through the armature 452 and its front contact of the final line relay 451, armature 453 and its back contact of the final intermediate relay 454, left winding of the final hunting relay 455, sequence switch contact 405, back contact and armature of the final supervisory line relay 456 to ground and back to battery. This energizes the final hunting relay 455 which, by the attraction 110 of its armature 458, closes a circuit from battery through the final finder rotary magnet 459 and the final finder holding magnet 460, in parallel, the left winding of relay 454, front contact and armature 458 of relay 455 to ground and back to battery, and also by its energization closes circuit from battery through the armature 452 and front contact of the relay 451, right winding of the relay 455, front contact and armature 458 of relay 457 of such relay, test brush 447 of the final line finder, to the test conductor 380 and thence to ground as heretofore traced. This circuit will be maintained so long as the test brush 447 is upon the test terminal of an idle intermediate finder or is connected to ground through the connected final test relay 462 of the final finder connected to an intermediate finder which is already busy. The closure of the circuit at the front con- 120 125 130

tact of the armature 458 of the relay 455 has energized the final intermediate relay 454 which has closed for itself a locking circuit from battery through the armature 452 and front contact of the relay 451, armature 453 and front contact of the relay 454, right winding of such relay to ground and back to battery, and has also energized the final finder rotary magnet and the final finder holding magnet. The energization of these magnets starts in motion the brushes of the final line finder and as heretofore noted, so long as the test brush 447 of the final line finder is upon the test terminal 10 of an idle or non-calling line the relay 455 will remain energized, it being noted that the original energizing circuit of this relay has been opened by the attraction of the armature 453 of the relay 454. The test 20 brush 447 of the final line finder is, like the test brushes of the finder heretofore considered, of such form that this circuit is not opened in passing from one test terminal to the next.

25 The rotation of the brushes of the final line finder will continue until the test brush 447 comes in contact with the test terminal connected to the "calling" intermediate finder. There being battery connected to 30 this test terminal instead of ground, the final hunting relay 455 will be deenergized and immediately opens the circuit of the final finder rotary magnet 459 and the final finder holding magnet 460 at the front contact of its armature 458. This brings to rest the brushes of the final line finder in contact with the terminals of the "calling" intermediate finder. The deenergization of the relay 455 has closed two circuits, the 40 first of which may be traced from battery through the final finder sequence switch 401, final finder sequence switch contact 425, left winding of the final supervisory relay 456, resistance 471, front contact and armature 461 of the relay 454, back contact and armature 458 of the relay 455 to ground and back to battery. This circuit causes the relay 456 to attract its armature, energizing the 45 sequence switch over a circuit including the sequence switch contact 425 and starting it in motion. The second circuit is from the battery on the test conductor 380 through the test brush 447 of the final line finder, armature 457 and its back contact of the 50 relay 455, final test relay 462, sequence switch contact 406, armature 474 and front contact device of the relay 451 to ground and back to battery. If at this time this final line finder is the only one the brushes 55 of which are in contact with the test terminal of the "calling" intermediate finder, the final test relay will be energized, but if on the other hand two or more final line finders have simultaneously come into contact with the terminals of this intermediate 60

finder the battery from the test conductor 380 would be so divided between the respective final test relays 462 that none of them will operate. It will be assumed for the present that but one of the final line finders 70 is in contact with the terminals of the "calling" intermediate finder.

It will be again assumed in connection with the operation of the final finder that the particular one shown is one of the group 75 selected by the hundreds wet point device shown on Fig. 3, and for convenience it will be assumed that this is one of the first group, although the operation of the hundreds wet point device was described as selecting the 80 second group. This assumption may be made as the operation of the final finders in the different groups is precisely the same and is made only on account of the convenience in showing the subsequent finder as 85 associated with the first group of the preceding wet point device rather than the particular group selected by such wet point device.

Before proceeding farther with the description of the operation of the final finder and its associated apparatus, it will be observed that when the circuit through the final test relay 462 is closed the intermediate line relay 351 was energized. The energization of this relay closed a circuit from battery through the intermediate sequence switch 301, left winding of the relay 351, sequence switch contact 321, armature 368 and front contact device of such relay 351 100 to ground and back to battery. In response to the closure of this circuit the intermediate sequence switch now moves from its sixth into its seventh position opening the circuit just traced at the sequence switch contact 105 321. At this time it will be noted that by the energization of the relay 351, the ground connection to the local wire 382 to the selected group was opened, stopping the movement of the unsuccessful final line finders 110 as will be hereinafter referred to.

The final sequence switch is now moving from its first to its third position. As the switch comes into its second position it provides a substitute ground connection for the 115 circuit of the final test relay 462 through the sequence switch contact 408 and the front contact and armature of such relay, this ground connection being maintained from this time until the nineteenth position 120 of the final sequence switch is reached. As the final sequence switch leaves its first position the sequence switch contact 403 is opened, and as the sequence switch leaves its second position it opens the sequence switch 125 contact 406 deenergizing the final line relay 451 so that from this time on the circuit for the final test relay 462 will depend upon the attraction of its own armature. As was the case with the intermediate test relay, 130

heretofore described, this final test relay 462 first acted as a test relay, but from now on will act as a disconnect relay, it being held operated so long as and only so long as battery is supplied to it over the test conductor 380 from the intermediate finder. When the final sequence switch reaches its third position a circuit is established from battery, armature 452 and back contact of the final line relay 451, final selecting relay 463, sequence switch contact 409, line conductor 441, brush 445, line conductor 365, brush 363, line conductor 298, primary sequence switch contact 231, test terminal 274, brush 542, secondary controller sequence switch contact 510, register restoring relay 529, back contact and armature 535 of the register cutoff relay 530, sequence switch contact 516, front contact and armature 585 of the tens transfer relay 584, sequence switch contact 507, to ground and back to battery. The closure of this circuit energizes the final selecting relay 463 and the register restoring relay 529. The energization of the register restoring relay 25 operates the tens register restoring magnet in a precisely similar way to that in which it operated the thousands and hundreds register restoring magnets, the circuit this time passing through the secondary controller sequence switch contact 517.

The energization of the final selecting relay 463 has closed a circuit from battery through the final sequence switch 401, final sequence switch contact 410, front contact and armature of the relay 463, back contact device 475 of the final line relay 451 to ground and back to battery. The closure of this circuit moves the final sequence switch into its fourth position, in which movement 40 none of the connections forming a part of the tens selection controlling circuit just described are affected, and consequently affecting in no way the energization of the final selecting relay 463 or the register restoring relay 529. In the fourth position of the final sequence switch, however, the sequence switch contacts 411 and 412 are closed. The closure of the sequence switch contact 411 has established a circuit from 45 battery through the brush-latch choosing magnet 68, sequence switch contact 411, front contact and armature of the relay 463, back contact device 475 of the relay 451 to ground and back to battery. The brush-latch choosing magnet being energized will cause the latch selecting spindle to rotate, in each position positioning itself to select and unlatch a different set of the selecting brushes 22, 24, 25. As this latch selecting 50 spindle revolves it operates the interrupter arm 56, the interrupter contacts 56, 59 being closed continuously while the spindle is moving from its normal position to its first latch selecting position, and thereafter while 55 it is moving from each latch selecting posi-

tion to the next, but being open in each of the latch selecting positions. When therefore the latch selecting spindle begins to move in response to the energization of the brush-latch selecting magnet 68, the interrupter contacts are closed and shunt the register restoring relay 529 while maintaining the final selecting relay 463 energized. The de-energization of the register restoring relay has caused the de-energization of the tens 70 register restoring magnet 587 preparatory to its driving the tens register disk a second step toward its normal position upon the subsequent energization of the register restoring relay 529.

When the latch selecting spindle reaches its first latch tripping position, in which position it is adapted to trip the first set of brushes upon the selector, the interrupter 56, 59 is reopened and the shunt around the register restoring relay removed. This relay is thereupon again energized accomplishing in a now well understood manner the second step of the tens register disk toward its normal position. The continued 80 movement of the latch selecting spindle causes the second closure of the interrupter and a second de-energization of the register restoring relay 529 in the well understood manner and with the well understood result. This alternate energization and de-energization of the register restoring relay 529, due to the alternate closing and opening of the interrupter 56, 59, will continue until the register restoring relay 529 has 100 been energized five times. When, however, this relay has been operated five times the tens register restoring magnet will have caused the tens register disk to have taken five steps in the reverse or counter-clockwise 105 direction and the tens register dial will now be again in its normal position, and consequently the contacts 583 will be opened and the contacts 588 will be closed. When now, due to the fifth closure of the interrupter 110 56, 59, the register restoring relay 529 is again de-energized, a circuit will be established from battery through the contacts 588, secondary controller sequence switch contact 589, left winding of the register cutoff relay 530, back contact and armature of the register restoring relay 529, to ground and back to battery. The consequent energization of the register cutoff relay 530 closes 115 a circuit for the secondary controller sequence switch which may be traced from battery through the sequence switch, front contact and armature 585 of the relay 530, sequence switch contact 516, front contact and armature 585 of the tens transfer relay 584, sequence switch contact 507 to ground and back to battery. The secondary controller sequence switch now moves from its 120 fourteenth to its sixteenth position, opening 125 the sequence switch contacts 516, 517 and 130

589, and closing, when it reaches the sixteenth position, the sequence switch contacts 518, 519 and 599.

In the meanwhile the latch-selecting spindle in its movement has reached the position in which it will select and unlatch the fifth set of selector brushes. As the latch spindle comes into this position the interrupter will be reopened and since the original energizing circuit of the final selecting relay 463 has been opened at the back contact of the register cutoff relay 530, the final selecting relay 463 will be deenergized opening at its front contact the circuit of 15 the latch-selecting magnet and closing at its back contact a circuit for the final sequence switch which may be traced as follows:— Battery through the final sequence switch 401, sequence switch contact 412, back contact 20 and armature of the relay 463, back contact device 475 of the relay 451 to ground and back to battery. The final sequence switch now moves into its fifth position, the energizing circuit therefore just traced being opened at the sequence switch contact 25 412 as soon as it leaves its fourth position. Furthermore the tens selection controlling circuit was opened, as soon as the sequence switch left its fourth position, at the sequence switch contact 409.

In the fifth position of the final sequence switch a circuit is closed from battery through the selector power magnet 62, sequence switch contact 413, back contact and armature of the relay 463, back contact device 475 of the relay 451 to ground and back to battery. The spindle of the selector which carries the various sets of brushes will now move and will continue to move 35 until the units interrupter brush 72 has left its coöperating insulated segment 46 and has come in contact with the grounded notched segment 50. A circuit will then be established from battery through the armature 40 452 and its back contact of the relay 451, final selecting relay 463, sequence switch contact 414, units interrupter brush 72, the segment 50 to ground and back to battery. The energization of the final selecting relay 463 by the closure of this circuit opens at the 45 back contact of the armature thereof the energizing circuit of the selector power magnet 62 and the spindle will stop. However, in this movement of the selector spindle 50 while the units interrupter brush was passing over the insulated segment 46 the row of brush latches have passed by the brush unlatching spindle 40 and the particular latch coöperating with the set position of 55 the brush unlatching spindle has been unlatched to release the set of selector brushes corresponding to the tens digit of the line desired, in the case assumed, the fifth set of selector brushes. The selector switch is now 60 ready for units selection.

The energization of the final selecting relay 463 just described has closed a circuit from battery through the final sequence switch 401, sequence switch contact 410, front contact and armature of the relay 463, 70 back contact device 475 of the relay 451 to ground and back to battery. The final sequence switch now moves from its fifth into its seventh position and in so doing establishes at the sequence switch contact 409 75 the units selection controlling circuit including the final selecting relay 463 and the register restoring relay 529. This units selection controlling circuit is precisely the same as the tens selection controlling circuit, except that the sequence switch contact 518 and the front contact and armature of the units transfer relay 594 are substituted for the sequence switch contact 516 and the front contact and armature of the tens transfer relay 584. The final selecting relay 463 being therefore reenergized in the seventh position of the final sequence switch, the same energizing circuit for the final sequence switch just described is reestablished and the sequence switch thereupon moves into its eighth position, but in so doing in no way disturbs the units selection controlling circuit which has just been described. In the well understood way the register restoring relay has by its energization caused the movement of the units register disk one step in its return to its normal position. The final sequence switch in coming into its eighth position has closed a circuit from battery through the selector power magnet 62, sequence switch contact 415, front contact and armature of the final selecting relay 463, 100 back contact device 475 of the relay 451 to ground and back to battery. By the energization of the selector power magnet, due to the closure of this circuit, the selector spindle begins to move trailing its selected and released brushes over the coöperating bank of terminals of the lines connected therewith. In this movement of the selector switch the units interrupter brush in passing over the notched plate 50 will be connected to ground at all times except when the brushes are centered upon the terminals of a 110 line. A shunt to the ground will therefore exist as soon as the final sequence switch comes into its eighth position which will deenergize the register restoring relay 529 until the selected and released brushes 23, 120 24, 25 of the selector switch rest upon the first set of line terminals in the bank of terminals with which they coöperate. At this time the connection to ground through the units interrupter brush and the notched 125 plate 50 will be broken and the shunt removed and the register restoring relay will be again energized. This movement of the selector switch and the alternate energization and deenergization of the register re- 130

storing relay will continue to take place with the accompanying stepping back of the units register disk to its normal position, until such register disk reaches its normal position. In the case assumed this will require ten energizations of the register restoring relay which will have occurred when the units interrupter brush places for the tenth time the shunt around the register restoring relay 529; such relay in its deenergization again closes a circuit for the register cutoff relay 530 which may be traced as follows:—Battery, contact 598, sequence switch contact 599, register cutoff relay 530, back contact and armature of the register restoring relay 529 to ground and back to battery. The energization of the register cutoff relay 530 opens by the attraction of its armature 535 the units selection controlling circuit, and therefore when the units interrupter brush is no longer connected to ground through the plate 50, the selector brushes being centered upon the tenth set of terminals of the coöperating bank of terminals, the final selecting relay 463 will be without battery and will be deenergized, opening at its front contact the circuit of the selector power magnet 62, thereby stopping the movement of the selector switch.

Before considering the further operation of the final finder apparatus and the selector switch the restoration to normal of the secondary controller will be considered. When the register cutoff relay 530 was energized as last described it closed a circuit from battery through the secondary controller sequence switch 501, front contact and armature 535 of the relay 530, sequence switch contact 518, front contact and armature 595 of the units transfer relay 594, sequence switch contact 507, to ground and back to battery. Due to the closure of this circuit the secondary controller sequence switch now moves to its nineteenth position. As soon as the sequence switch 501 leaves its sixteenth position the circuit including the secondary controller test relay 558 and the secondary controller line finder test brush 543 is destroyed by the opening of the sequence switch contact 506 for the purpose of causing the deenergization of the secondary controller test relay 558 and the primary intermediate relay 261. In leaving the sixteenth position, furthermore, the secondary controller sequence switch has opened the circuit of the register cutoff relay 530 at the sequence switch contact 599 and this relay is therefore deenergized. When the secondary controller sequence switch therefore reaches its nineteenth position, the circuit is closed through the sequence switch contact 539 and the back contact and armature 536 of the relay 530 and the sequence switch therefore continues its movement into its first or normal position, and is now ready to

associate itself and coöperate with some other primary finder or the same primary finder on a subsequent call.

When the secondary controller sequence switch left its sixteenth position it will be remembered that the ground connection was removed from the test terminal 275 leading to the primary finder apparatus, and that the primary intermediate relay 261 was thereupon deenergized. By the retraction of the armatures of this relay a circuit was closed from battery through the armature 252 and its front contact of the relay 251, armature 253 and back contact of the relay 261, sequence switch contact 237, the primary selecting relay 267, sequence switch contact 208, armature 268 of the primary line relay 251 to ground and back to battery. This causes the energization of the relay 267 which in turn closes a circuit for and thereby energizes the primary sequence switch 201, and causes it to move into its fourteenth position. This circuit may be traced from battery through the sequence switch, sequence switch contact 219, front contact 90 and armature of the relay 267 to ground and back to battery. In this movement of the primary sequence switch, the sequence switch contacts 214, 227 and 222 are opened, and the sequence switch contacts 223 and 206 95 are closed. The opening of the sequence switch contact 214 has removed battery from the test conductor leading to the test terminals individual to this primary finder in the group of secondary controller line 101 finders with which it is associated, and the closing of the sequence switch contact 206 has applied ground to these test terminals. By these operations the terminals 273, 274 and 275 of this primary finder are made to 105 test idle or non-calling, and any hunting secondary controllers of its associated group will pass over the terminals of this primary finder without stopping thereon. The closure of the sequence switch contact 223 has 110 connected to the line conductor 265 a ground connection through the retardation coil 277, and the calling half of the talking circuit is now complete.

It will be noted that while the primary 115 sequence switch is passing from its thirteenth to its fourteenth position the sequence switch contact 224 is closed, which places a ground upon the line conductor 265 through the resistance 288, sequence switch contact 120 224, back contact and armature 262 of the relay 255 to ground. This ground connection prevents the deenergization of the primary supervisory line relay 272 between the time that the sequence switch contact 222 125 which originally formed a part of the circuit thereof is opened and the sequence switch contact 223, which is substituted therefor, is closed. It will be further noted that when the primary sequence switch 130

moves into its sixteenth position, which, as will be hereinafter pointed out, is the talking position of the primary finder apparatus, the sequence switch contact 224 is opened 5 and the line conductor 265 is at that time connected to ground only through the sequence switch contact 223 and the retardation coil 277.

It will be remembered that the last described operation of the final finder and selector was when at the close of units selection and while the final sequence switch was in its eighth position, the final selecting relay 463 was deenergized to open the circuit 10 of the selector power magnet 62, at which time the selected brushes of the selector switch were centered on and in contact with the terminals of the desired line. At this time by the deenergization of the final selecting relay a circuit was established from battery through the final sequence switch 401, sequence switch contact 412, back contact and armature of the relay 463, back contact device 475 of the relay 451 to ground 15 and back to battery. The final sequence switch will now move from its eighth to its twelfth position without stopping in its ninth, tenth or eleventh positions, but in passing through its ninth position it will. 20 test the condition of the called line in the following manner. A ground connection is made to the selected test brush 25 of the selector switch through the back contact device 475 of the final relay 451, right winding 25 of the final supervisory line relay 456, and sequence switch contact 418. By referring to Fig. 1 it will be seen that a subscriber's line when idle has its multiple test conductor 199 connected to ground through the left 30 winding of the cutoff relay 104 and the armature and back contact of the subscriber's line relay 102. On the other hand, whenever the line is busy this multiple test terminal will be connected to battery through the left winding of the cutoff relay 104 and the armature and front contact of the energized subscriber's line relay 102. It will therefore be apparent that if the line desired is idle the final sequence switch will 35 pass through its ninth position without any change in the apparatus associated therewith; whereas if the line desired is busy an energizing circuit will be closed through the right winding of the final supervisory line 40 relay 456.

Attention should here be directed to the fact that the cutoff relay 104 of all busy lines is energized whether its associated line is a calling line, in which case the cutoff relay and the subscriber's line relay have been operated in the manner already described, or whether the line be a called line in which case the subscriber's line relay is operated in a manner hereinafter to be described. In any event, therefore, if the line

is busy battery is connected to its test terminals 29 in the final switches in which this line appears through its multiple test conductor 199 and when the test brush 25 is in connection therewith and the sequence 70 switch contact 418 closed the relay 456 will be energized. If on the other hand the line is idle the multiple test conductor 199 will be connected to ground and no energization of the relay 456 can take place in circuit 75 therewith.

Assuming first that the desired line is idle, the final sequence switch has passed through its ninth position without change in the condition of the apparatus associated therewith and with the final selector, and comes to its tenth position. In passing through the tenth position the closure of the final sequence switch contact 419 has established a circuit from battery through the subscriber's line relay 102 of the called line, back contact device of the cutoff relay 104 of the called line, line conductor 105, multiple line conductor 198, terminal 28 of the called line, selector brush 24, armature 466 and front contact of the ringing control relay 464, final sequence switch contact 419, back contact device 475 of the final line relay 451, to ground and back to battery. 80 This circuit will energize the subscriber's line relay of the called line to make such line test busy in all of the other selectors in which its terminals appear. Upon the energization of the subscriber's line relay 102 of the called line, moreover, a circuit 85 was established from battery through the front contact and armature of such relay, tone relay 108, and back contact and armature of the ground relay 109 to ground and back to battery. This circuit energizes the 90 relay 108 which, by its armature 114, places a ground upon the test conductor of the called line appearing in all of the primary line finders in which this line appears so that it will test busy, that is, non-calling to 95 all of the primary finders in which it appears. The energization of this relay 108 also has closed the normal opening connection between the two sections of the line conductor 106 of the called line. The energization of the subscriber's line relay of the called line has also closed a circuit from battery through the front contact and armature 112 of such relay 102, left winding 100 of the cutoff relay 104, multiple test conductor 199 and test terminal 29, all of the called line, test brush 25 of the selector switch, resistance 472, sequence switch contact 420 to ground and back to battery. This circuit energizes the cutoff relay 104 105 of the called line, which by the attraction of its armature 103 clears the called line of all bridging connections, but at the same time maintains an energizing circuit for the subscriber's line relay 102 of the called line 110 115 120 125 130

through the armature 103 and front contact of such cutoff relay and the resistance 121.

In tracing the energizing circuit of the subscriber's line relay of the called line it will be seen that such circuit went through the armature 466 and front contact of the ringing control relay 464. It will be observed that this relay was first energized as soon as the final sequence switch 401 came into its eighth position and thereupon attracted its armature. It will be remembered that it was while the sequence switch was in its eighth position that the movement of the selector switch trialed the set of selected selector brushes over the line terminals in the bank of terminals adapted to operate therewith. The attraction of the armatures of the ringing control relay 464 has cleared the selected brushes 23 and 24 from all connections to either ground or battery, while they are moving. The circuit for energizing this ringing control relay may be traced from battery through the sequence switch contact 416, lower winding of the ringing control relay 464, sequence switch contact 417, back contact and armature 461 of the relay 454, back contact and armature 458 of the relay 455 to ground and back to battery. This circuit will be maintained until the final sequence switch leaves its eleventh position and therefore the ringing control relay will remain energized in the tenth position, the position in which the circuit to the subscriber's line relay of the called line, which we have above traced, was established.

It will be observed that the circuit hereinbefore traced for the cutoff relay 104 of the called line will be maintained through the sequence switch contact 420 until the final sequence switch leaves its fifteenth position, thus assuring that the relays 104, 102 and 108 of the called line will be maintained energized during the ringing of such line and conversation thereover.

The desired line having been tested and found idle, it is now necessary that ringing current should be sent thereover to signal the called subscriber, and the twelfth position of the final sequence switch is therefore the ringing position. Upon coming into the twelfth position the final sequence switch has opened the sequence switch contact 416 and closed the sequence switch contact 423. This has opened the original energizing circuit of the ringing control relay 464 and has closed an intermittent circuit for such relay through the machine ringing interrupter 467. Under the influence of this interrupter the ringing control relay will be energized and deenergized at predetermined intervals. When this relay is in its energized condition, the final sequence switch now being in its twelfth position, a circuit is established

from the grounded source of ringing current 468 through the sequence switch contact 421, front contact and armature 466 of the ringing control relay 464, line conductor 444, selected brush 24, terminal 28, out over the multiple line conductor 198 of the called line, line conductor 105 of such line, called subscriber's substation apparatus including the usual condenser and ringer, line conductor 106, multiple conductor 197, terminal 27, selected brush 23, line conductor 443, armature 465 and front contact of the ringing control relay 464, sequence switch contact 422, back contact and armature 461 of the relay 454, back contact and armature 458 of the relay 455 to ground and back to battery. While the ringing control relay is in its deenergized condition there is battery connected to the selected brush 24 and ground connected through the final supervisory relay 456 to the selected brush 23. When therefore the called subscriber responds by removing his receiver from the switch hook 151, thereby establishing a path for direct current around the condenser at his substation, a circuit will be established during a period of the deenergization of the ringing control relay 464 from battery, through armature 452 and back contact of the final line relay 451, retardation coil 469, back contact and armature 466 of the ringing control relay 464, line conductor 444, selected brush 24, terminal 28 of the called line, out over such line and back by terminal 27, selected brush 23, line conductor 443, armature 465 and back contact of the ringing control relay 464, sequence switch contact 424, right winding of the final supervisory line relay 456, back contact device 475 of the relay 451 to ground and back to battery. The closure of this circuit energizes the final supervisory line relay 456 which closes by the attraction of its armature a circuit from battery through the final sequence switch 401, sequence switch contact 425, front contact and armature of the now energized relay 456 to ground and back to battery. The final sequence switch now moves into its fifteenth position which is the talking position.

The final sequence switch in passing through its thirteenth and fourteenth positions, which it did under influence of the special contact 402, closed the sequence switch contact 426. The closure of this contact established a circuit from battery through the primary sequence switch contact 216, relay 267, sequence switch contact 218, sequence switch contact 231, line conductor 298, intermediate finder brush 363, line conductor 365, final finder brush 445, line conductor 441, final sequence switch contact 426, back contact and armature 461 of the relay 454, back contact and armature 458 of the relay 455 to ground and back to

battery. The closure of this circuit energizes the primary selecting relay 267 which by the attraction of its armature closes a circuit for the primary sequence switch which 5 may be traced from battery, primary sequence switch 201, sequence switch contact 219, front contact and armature of the relay 267 to ground and back to battery. The primary sequence switch now moves into its 10 sixteenth position closing the sequence switch contact 234.

The primary finder apparatus is now in its talking position and as soon as the final sequence switch on coming into its fifteenth 15 position to which it is now moving closes the sequence switch contacts 427 and 428 the entire connection will be established. The conversation between the connected subscribers may now take place, it being observed 20 that battery is supplied to the calling subscriber over the circuit heretofore traced for the supervisory line relay 272 and for the called subscriber over the circuit which has heretofore been traced for the final 25 supervisory relay 456. It will be furthermore observed that these two sources of current are separated in the line circuit by the condensers 476 and 477 as is the usual and standard practice.

30 Before proceeding to the description of the disconnecting operation it will be observed that the ringing control relay 464 during conversation is maintained deenergized to prevent the interruption of the talking circuit, the energizing circuits of its upper and lower windings being open at the front contact of the armature 453 of the relay 454 and at the back contact of the relay 456 respectively.

40 It will be further observed that the battery supply bridges for both the calling and the called subscribers are connected through retardation coils 277 and 469 on the one side and the supervisory relays 272 and 456 on 45 the other side so that voice currents will not be shunted through these battery supply bridges.

When either the calling or the called subscriber desires disconnection he replaces his 50 receiver upon the switch hook 151. Assuming first that the called subscriber is the first to hang up his receiver the circuit of the final supervisory relay 456 will be opened and on deenergizing will by the retraction 55 of its armature close a circuit from battery through the final sequence switch 401, sequence switch contact 429, back contact and armature of relay 456 to ground and back to battery, and also a circuit from battery 60 through sequence switch contact 416, lower winding of the relay 464, sequence switch contact 431, back contact and armature of the relay 456 to ground and back to battery. The first of these circuits energizes the sequence 65 switch to start it in motion and the

second of these circuits energizes the ringing control relay 464 which by the attraction of its armatures opens the talking circuit and clears the conductors 443 and 444 and their connected selector brushes 23 and 24 from all connection to ground and battery. The maintenance of this circuit for the relay 464 through the eighteenth position of the final sequence switch in which period the selector has been entirely restored 75 to its normal condition prevents interruption or interference with talking or signaling over busy lines, the terminals of which the selected brushes 23, 24 trail over in their movement to normal position. The final 80 sequence switch will now move out of its fifteenth position and under the influence of the special contact 402 into its seventeenth position. When the final sequence switch came into its sixteenth position the circuit 85 was closed from battery through armature 452 and back contact of the relay 451, relay 463, sequence switch contact 430, through the brush-latch selecting spindle restoring cam 470, to ground and back to battery. 90 This circuit is closed owing to the fact that the brush-latch selecting mechanism is not in its normal position in which position, and in which position only, the restoring cam 95 470 has its insulated segment in contact with the coöperating brush and no circuit will be established through such cam. When such cam, however, is in any other position than its normal position, due to the movement of the brush-latch selecting spindle from its 100 normal position, a ground will be established through such cam. This brush-latch selecting spindle restoring cam may be attached to or controlled by the spindle 40 in any preferred way, it only being necessary that 105 contact should be closed through it to ground when the spindle 40 is in any but its normal position and open when in its normal position. The particular diagrammatic showing 110 of this cam upon the drawings is for convenience only. Due to the closure of this circuit through the cam 470 which is maintained in the seventeenth position of the final sequence switch, the relay 463 will be energized and by the attraction of its armature will close a circuit from battery through the brush-latch selecting spindle rotary magnet 68, sequence switch contact 411, front contact and armature of the relay 463, back contact device 475 of the relay 451 to ground 115 and back to battery. This will cause the energization of the power magnet 68 which will cause the latch spindle to move, which movement will continue until the ground 120 circuits through both the restoring cam 470 and the interrupter 56, 59 are opened. When 125 this is the case the spindle 40 will be in its normal position, and the movement of such spindle will be stopped by the deenergization of the relay 463 the circuit of which, 130

it will be remembered, passed through the cam 470, and the consequent opening of the circuit of the power magnet 68 at the front contact of such relay 463.

5 The retraction of the armature of the final selecting relay 463 upon this deenergization has closed a circuit from battery through the final sequence switch 401, sequence switch contact 412, back contact and armature of the relay 463, back contact device 475 of the relay 451 to ground and back to battery. The final sequence switch will now move into its eighteenth position. In this position of the final sequence switch a circuit is 10 closed from battery through the selector power magnet 62, sequence switch contact 413, back contact and armature of the relay 463, back contact device 475 of the relay 451 to ground and back to battery. By the closure of this circuit the selector power magnet will be energized and the brush carrying spindle will rotate until it has reached again its initial position, that is, until the units interrupter brush 72 comes into contact 15 with the insulated segment 46, at which time the circuit is closed from battery through the armature 452 and back contact of the final line relay 451, final selecting relay 463, insulated segment 46, units interrupter brush 20 72, sequence switch contact 432 to ground and back to battery. In this movement of the brush carrying spindle just described it should be observed that the selected brushes 23, 24, 25, have been restored to their latched 25 position, in which position they will not trail over the line terminals in the next operative movement of the selector, by co-operation with the roller 69. The final selecting relay will be energized by the closure of this 30 circuit and by the attraction of its armature will open the circuit of the selector power magnet 62, which thereupon is deenergized and the selector brush carrying spindle comes to a stop. The energization of the 35 relay 463 has also closed a circuit from battery through the final sequence switch 401, sequence switch contact 410, front contact and armature of the relay 463, back contact device 475 of the relay 451 to ground and 40 back to battery. The final sequence switch now moves into its nineteenth position.

On coming into its nineteenth position the final sequence switch has by the opening of the sequence switch contact 432 interrupted the energizing circuit of the final selecting relay 463. The deenergization of this relay 463 and the consequent retraction of its armature has closed a circuit to initiate the restoration of the primary finder apparatus 45 and the intermediate finder apparatus. This circuit may be traced from battery through primary sequence switch contact 215, armature and front contact of the primary supervisory line relay 272 through such relay, 50 through the left winding of the primary test

relay 286, current being shunted through this test relay by the non-inductive resistance 289 inserted in the line conductor 296, primary sequence switch contact 230, line conductor 299, intermediate finder brush 364, line conductor 366, final finder brush 446, line conductor 442, final sequence switch contact 433, resistance 473, back contact and armature of the final selecting relay 463, back contact device 475 of the final line relay 451 to ground and back to battery. After the closure of this circuit the final finder and its associated apparatus will await, before their further restoration to normal, predetermined stages in the restoration of the primary finder and the intermediate finder apparatus, since it will be observed that the further operations of the final finder now depend upon the removal of battery from the test conductor 380 leading to the intermediate finder apparatus.

It may be here noted that in the restoration of each of the respective finder apparatus no movement of the brushes of the associated line finders is necessary since they have no normal position and may without interfering in any way with the proper operation of the system remain upon the terminals with which they were last operatively connected, it being observed that in each case the line conductor brushes have no connections associated therewith in the normal position of the respective apparatus which will in any way effect the terminals upon which they may happen to rest.

The energization of the primary test relay 286 in the sixteenth position of the primary sequence switch as described will not at this time cause the energization of the primary hunting relay 255 by the closure of the circuit from battery through the right winding of the primary test relay 286, front contact and armature of such relay, resistance 287 and left winding of the primary hunting relay 255, for the reason that this left winding of the hunting relay is shunted by the sequence switch contact 233. The closure of the primary test relay will, however, close a second circuit from battery through the right winding of such relay 286, front contact and armature of such relay, sequence switch contact 232, primary selecting relay 267, sequence switch contact 208, armature 268 of the primary line relay 251 to ground and back to battery, it being remembered that this line relay 251 is now maintained energized by ground on the test brush 358 of the connected intermediate finder apparatus. The primary selecting relay 267 will now be energized and closes a circuit from battery through the primary sequence switch 201, sequence switch contact 219, armature and front contact of the relay 267 to ground and back to battery. The primary sequence switch will now move

115

120

125

130

into its eighteenth position and in leaving its sixteenth position, by opening the sequence switch contact 220 it removes ground from the primary line finder test brush 258, 5 and thereby opens the circuit through the right winding of the cutoff relay 104 of the calling line. This will cause the deenergization of this relay 104 and the retraction of its armatures. The tone relay 108 of the 10 calling line being at this time energized, the tone will be received by the calling subscriber through resistance 116, front contact and armature 114 of the tone relay 108, armature 115 and back contact of the cutoff 15 relay 104, service meter 119, line conductor 106, front contact and armature 107 of the tone relay 108, line conductor 106, subscriber substation apparatus, line conductor 105 and the subscriber's line relay 102, battery and 20 to ground. This tone will be heard in the receiver of the calling subscriber who will therefore know that the calling subscriber has hung up his receiver and that disconnection is going on.

25 When the primary sequence switch reaches its eighteenth position, it closes the sequence switch contact 236 thereby applying battery to the test conductor of the calling line and the circuit is established from such battery 30 through the sequence switch contact 236, back contact and armature 256 of the primary hunting relay 255, conductor 257, test brush 258 of the primary finder, test conductor 110 of the calling line, armature 115 35 and back contact of the cutoff relay 104 of the calling line, service meter 119 of the calling line, line conductor 106, brush 263 of the primary line finder, line conductor 265, sequence switch contact 223, retardation coil 40 277 to ground and back to battery. This will operate the service meter, the call having been a successful one.

When the primary sequence switch 201 came into its seventeenth position it closed 45 and maintained closed in its eighteenth position the sequence switch contacts 235 and 216, and in its eighteenth position closed the sequence switch contact 225. A circuit was therefore first established from battery 50 through the sequence switch contact 216, primary selector relay 267, off-normal switch 283 of the hundreds wet point device, sequence switch contact 235 to ground and back to battery. This energizes the primary 55 selecting relay 267, which by the attraction of its armature closes when the sequence switch reaches its eighteenth position a circuit from battery through the thousands wet point rotary magnet 278, sequence switch contact 225, front contact and armature of the relay 267 to ground and back to battery. The thousands wet point device will now move until it returns into its normal position, in which position the contacts of none 60 of the groups controlled thereby will be op-

erated, this wet point device being controlled in its return and stopped in its normal position by the off-normal switch 283 and the interrupter contacts 284, both of which are only open in the normal position of the device. This control is exercised through the primary selector relay 267 which, as soon as the off-normal switch 283 and the interrupter contacts 284 are both opened, is deenergized and immediately opens at its front 70 contact the energizing circuit of the wet point device rotary magnet 278 and thereby stops this device in its normal position. The retraction of the armature of the primary selecting relay 267 has also closed a circuit 75 from battery through the primary sequence switch 201, sequence switch contact 229, back contact and armature of the relay 267 to ground and back to battery. The primary sequence switch now moves into its first or 80 normal position. When the primary sequence switch reaches its first position the sequence switch contact 210 is closed and shunts the right winding of the primary test relay 286. This causes the deenergization 85 of this relay and the primary finder apparatus is now all in its normal condition.

When the primary sequence switch 201 in its movement from its sixteenth position, as above described, removed the battery from 90 the test conductor 280 by opening the sequence switch contact 226 on such device, it opened the energizing circuit of the intermediate test relay 386. Such relay 386 by its deenergization and the retraction of its 100 armature closes a circuit from battery through the intermediate sequence switch 301, sequence switch contact 319, back contact and armature of the intermediate test relay 386 to ground and back to battery. Due to the closure of this circuit the intermediate sequence switch now moves into its 105 tenth position and in such position closes the sequence switch contacts 314 and 315. Furthermore in passing into its eighth position 110 it closed and maintained closed in its tenth position the sequence switch contacts 306 and 312. Circuit is now established from battery through back contact and armature of the intermediate line relay 351, which was 115 deenergized by the opening of the sequence switch contact 316 as the intermediate sequence switch left its seventh position, intermediate selecting relay 367, sequence switch contact 306, off-normal switch 383 to ground 120 and back to battery. This off-normal switch 383 is at this time closed, the hundreds wet point device being in one of its stages or positions other than its normal position, having been moved to select the final finders 125 associated with the second hundred of the selected thousands lines of the exchange, and the intermediate selecting relay will therefore be energized and will close a circuit from battery through the hundreds wet 130

point device rotary magnet 378, sequence switch contacts 315, front contact and armature of the relay 367, back contact device 381 of the relay 351 to ground and back to battery. The hundreds wet point device, due to the closure of this circuit and the energization thereby of its rotary magnet, will now move and under control of the off-normal switch 383 and interrupter contacts 384 will continue to move until it is again in its normal position, when the opening of both the off-normal switch 383 and the interrupter contacts 384 deenergizes the relay 367 which, in the retraction of its armature, opens at its front contact the energizing circuit of the hundreds wet point device rotary magnet 378 and the hundreds wet point device will come to rest in its normal position with none of the contacts of the respective groups controlled thereby operated. This deenergization of the intermediate selecting relay 367 just described has closed a circuit from battery through the intermediate sequence switch 301, back contact and armature of the relay 367, back contact device 381 of the relay 351 to ground and back to battery. The intermediate sequence switch will now move into its first or normal position opening the sequence switch contacts 306, 314, 315 and 312, and closing the sequence switch contacts 303, 304, 305, 306, 307, 308, 309 and 320. The intermediate finder apparatus is now in its normal condition.

As soon as the intermediate finder sequence switch 301 left its seventh position it removed by the opening of the sequence switch contact 316 the battery which had in the sixth and seventh positions of this sequence switch been applied to the test conductor 380 extending to the connected final finder apparatus, and on coming into its eighth position it had connected such conductor to ground through the sequence switch contact 325. The removal of this battery from the test conductor opened the circuit of the final test relay 462 of the final finder apparatus which thereupon became deenergized. It will also be noted that the connection of ground to the test conductor extending from the intermediate finder apparatus to the final finder apparatus has made the test terminals of this intermediate finder apparatus, where they appear in the final line finders, of such electrical character that they will test non-calling, and such final line finders cannot therefore seize the terminals of this intermediate finder until after such ground is removed which occurs when the intermediate finder sequence switch reaches its normal position.

It will also be observed that a similar operation took place in the restoration of the thousands wet point device. In that case the sequence switch contact 228 was closed

to connect ground to the various test conductors 280 during the restoration of the hundreds wet point device to normal.

The deenergization of the final test relay 462 has closed a circuit from battery through the armature 452 and back contact of the final line relay 451, final selecting relay 463, sequence switch contact 434, back contact and armature of the final test relay 463 to ground and back to battery. The closure of this circuit energizes the relay 463 which, by the attraction of its armature, closes a circuit from battery through the final sequence switch 401, sequence switch contact 410, front contact and armature of the final selecting relay 463, back contact device 475 of the final line relay 451 to ground and back to battery. The closure of this circuit causes the final sequence switch to move into its normal position and the entire final finder apparatus and its associated selector are again in their normal condition.

The entire apparatus which was used in the establishment of the desired connection is now entirely restored and in its normal condition.

Disconnection from calling end.—Recurring now to the time when the talking circuit was established, it will be assumed that the calling subscriber first restores his receiver to the switch hook. This act on his part will cause the deenergization of the primary supervisory line relay 272 since it will be recalled that the circuit of this relay included the closed switch hook 151 at the calling subscriber station. It will also be recalled that the primary finder sequence switch is at this time in its sixteenth position. The deenergization of the supervisory line relay will therefore close two circuits the first of which may be traced as follows:—from battery through the sequence switch contact 215, back contact and armature of the supervisory line relay 272, resistance 287, left winding of the primary hunting relay 255 to ground and back to battery, but since this left winding of the primary hunting relay 255 is shunted by a circuit through the sequence switch contact 233 and back contact and armature 262 of such primary hunting relay, this relay will not be energized. The second circuit closed by the deenergization of the primary supervisory line relay 272 extends from battery through the sequence switch contact 215, armature and back contact of the primary supervisory line relay 272, the sequence switch contact 232, primary selecting relay 267, sequence switch contact 208, armature 268 of the primary line relay 251 to ground and back to battery. The closure of this circuit energizes the primary selecting relay 267 which attracts its armature and closes circuit from battery through the primary sequence switch 201, sequence switch

130

contact 219, front contact and armature of the relay 267 to ground and back to battery. The primary sequence switch thereupon moves from its sixteenth into its eighteenth position and from that position the primary finder apparatus restores itself precisely in the manner heretofore described. In such restoration, as before described, battery is removed from the test conductor leading to the connected intermediate finder and ground substituted therefor. As a result of the removal of battery from the test conductor 280 leading thereto the connected intermediate finder apparatus is restored to normal in the manner heretofore described, in such operation removing battery from the test conductor leading to the connected final finder and substituting a ground thereon.

20 The removal of the battery from the test conductor leading to the connected final finder whose sequence switch is now in the fifteenth or talking position has deenergized the final test relay 462, which, by the retraction of its armature, has closed a circuit from battery through the right winding of the final line relay 451, sequence switch contact 435, back contact and armature of the final test relay 462 to ground and back to battery. The energization of the relay 451 due to the closure of this circuit establishes a circuit from battery through the final sequence switch 401, left winding of the final line relay 451, sequence switch contact 436, armature 424 of the final line relay 451 to ground and back to battery. The closure of this circuit moves the final sequence switch from its fifteenth into its seventeenth position, and the restoration of the final finder apparatus and its associated selector will take place precisely as heretofore described, except that the restoration will not be suspended in the nineteenth position while the primary finder apparatus and intermediate finder apparatus are being restored because such restoration has already taken place or is taking place and the final test relay 462 is already deenergized. In the manner described therefore the restoration of the calling subscriber's receiver to its switch hook has restored the entire apparatus used in this connection to its normal condition.

Operation when called line tests busy.—Assuming now that when the selected brushes of the selector switch came to rest in contact with the terminals of the desired line, this line was busy. It will be recalled that the multiple test conductors of all busy lines have battery applied thereon in the manner hereinbefore described. When then the final sequence switch was moved out of its eighth position by the deenergization of the final selecting relay 463 in that position the sequence switch in the ninth or test position closes a circuit from battery on the busy

test terminal 29 through the test brush 25 of the selected set of brushes on the selector, the sequence switch contact 418, right winding of the final supervisory line relay 456, back contact device 475 of the final line relay 451 to ground and back to battery. The energization of the final supervisory line relay, due to the closure of the circuit just traced, causes the attraction of its armature and a circuit is established from battery through the right winding of the final line relay 451, sequence switch contact 437, left winding of the final supervisory line relay 456, front contact and armature of such relay to ground and back to battery. This circuit serves as a locking circuit for the final supervisory line relay and also as an energizing circuit for the final line relay 451, which thereupon attracts its armature and closes a circuit from battery through the final sequence switch 401, through the left winding of the final line relay 451, sequence switch contact 436, armature 474 of the relay 451 to ground and back to battery. This circuit will be maintained through the fifteenth position of the final sequence switch and the sequence switch will then be continuously energized and move without stopping into its seventeenth position, its movement through the sixteenth position being controlled by the special contact 402.

Since the desired line has tested busy and is therefore already engaged, it will be necessary to provide some means whereby ringing current will not be applied to the terminals of this line while the final sequence switch 401 is passing through its twelfth position. This result is accomplished in this way. It will be recalled that upon the energization of the final supervisory line relay 456 by the attraction of its armature, it closed a locking circuit for itself through its left winding and through the right winding of the final line relay 451. This caused the energization of the final line relay 451 which attracted its armatures and closed a circuit through its left winding and the final sequence switch, which circuit will be maintained until the final sequence switch has left its fifteenth position (see sequence switch contact 436). When now the final sequence switch reaches its eleventh position, a circuit will be established from battery through the armature 452 and its front contact of the final line relay 451, sequence switch contact 438, right winding of the final intermediate relay 454 to ground and back to battery. In response to the closure of this circuit the final intermediate relay 454 attracts its armatures and closes a locking circuit for itself which may be traced from battery through armature 452 and front contact of the final line relay 451 which, it will be recalled, is maintained energized by the circuit through its left wind-

ing, armature 453 and its front contact of the final intermediate relay 454, the right winding of such relay to ground and back to battery. This circuit will be maintained 5 through the fifteenth position of the final sequence switch and therefore the energizing circuit for the lower winding of the ringing control relay 464 will be maintained open from the eleventh to the fifteenth position of the final sequence switch at the back contact of the armature 461 of the final intermediate relay 454. It will be further noted that in these positions battery will not be placed upon the terminals of the desired line even 10 though in the eleventh and twelfth positions of the final sequence switch, the ringing control relay 464 will be deenergized, the battery connection through the retardation coil 469 being open at the back contact of the armature 452 of the final line relay 451 and the ground connection being open on account 15 of the attraction of the armature 474 of the same relay. However, after the final sequence switch has passed the twelfth position 20 an energizing circuit will be established for the ringing control relay 464 to cause it to attract its armatures 465 and 466 so that connection will be broken at the back contacts of the armature thereof, such energizing 25 circuit extending from battery through the armature 452 and its front contact of the final line relay 451, armature 453 and its front contact of the final intermediate relay 454, sequence switch contact 439, upper winding of the ringing control relay 464 to ground and back to battery. This circuit 30 will be maintained and the relay 464 energized thereby through the fifteenth position of the sequence switch. Furthermore it will 35 be observed that this ringing control relay 464 will now be maintained continuously energized until the selector switch has been restored to normal by the establishment of a circuit through its lower winding, the sequence 40 switch contacts 416 and 431 and the back contacts and armature of the final supervisory relay 456 precisely as has been heretofore described in connection with the restoration after a successful call. This circuit 45 in this case, however, will be established in the fourteenth position of the final sequence switch since the final supervisory relay became deenergized as the sequence switch left its eleventh position by the opening 50 of the sequence switch contact 437, it being further noted that the armature 465 has been attracted by this time in order to prevent any interference with the electrical 55 condition of the desired line.

60 In the eleventh position of the final sequence switch, the current, passing through the right winding of the final line relay 451, will divide after passing through the sequence switch contact 437, a part going 65 through the left winding of the final supervisory relay 456 and a part passing through the front contact and armature 461 of the final intermediate relay 454. To prevent the circuit through this armature 461 from shunting and thereby deenergizing the final supervisory relay 456 in the eleventh position of the sequence switch, the resistance 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

Since, however, the primary hunting relay 255 is maintained energized from the sixteenth to the nineteenth positions of the primary sequence switch the closure of the sequence switch contact 233 cannot shunt the left winding of this relay, and furthermore the armature 256 of this relay being attracted, battery from the sequence switch contact 236 will not be applied to the test conductor of the calling line, and the service meter of the calling line will therefore not be operated, this having been an unsuccessful call.

In all other regards the restoration of the apparatus will be, under the circumstances assumed, as has been hereinbefore described.

Attempted simultaneous seizure by line finders.—Whenever, as has been hereinbefore referred to, the brushes of two line finders, such, for example, as primary line finders, reach the terminals of a calling line simultaneously, the hunting relays 255 of each primary finder will be deenergized and parallel circuits will be established from the test conductor 110 through the respective test brushes 258, armature and back contact of the hunting relays 255, sequence switch contacts 207, the respective selecting relays 267, sequence switch contacts 208, and the armature of the respective line relays 251 to ground and back to battery. The current, however, since it passes through the selecting relays 267 in parallel, will be so divided that neither of these selecting relays will attract its armature. When therefore the primary sequence switch 201 is passing through its third and fourth position, a circuit will be closed due to the deenergization of the hunting relay 255 from the battery 101 through the subscriber's line relay 102, contacts of the cutoff relay 104, line conductor 105, line conductor 264, through the left winding of the test relay 286, sequence switch contact 211, back contact and armature of the selecting relay 267 to ground and back to battery. This circuit will exist in connection with both of the primary finders. The closure of this circuit will energize the test relay 286 which, by attracting its armature, has closed a locking circuit for itself and an energizing circuit for the hunting relay 255 from battery through the right winding of the test relay 286, front contact and armature of such relay, resistance 287, left winding of the hunting relay 255 to ground and back to battery. The energization of the hunting relay at this time closes a circuit for the primary sequence switch 201 through the sequence switch contact 238, which circuit, since it is maintained continuously from the third to the sixteenth positions, will drive the primary sequence switch into its eighteenth position from whence it will immediately restore to its first or normal position on account of the

fact that the off-normal switch 283 is not closed. In connection with this restoration it will be noted that the circuit for the hunting relay 255 having been established in the third or fourth position will be maintained until the test relay 286 is deenergized by the closure of the sequence switch contact 210.

It will be observed from this description that if two line finders simultaneously attempt to seize the terminals of the calling line they will both be positively and expeditiously returned to normal. It will be noted furthermore that owing to the continued energization of the hunting relay 255 and the attraction of its armature 256 after the third position of the sequence switch no ground will be placed upon the test brush 258 by either of these finder apparatus. Therefore in spite of the connection of these test brushes with this test conductor 110, the test terminal of the calling line will not test busy to the test brush of any other primary finder the brushes of which may come in contact with the terminals of the calling line while the two finders which originally came in contact with it are in process of restoring to normal. If, however, the brushes of no other primary finder have come in contact with the terminals of the calling line while the two finders which first came in contact with the terminals of such line are restoring to normal, the first one of such primary finders that comes into its normal position will seize this calling line to the exclusion of the other. This occurs for the reason that the selecting relay of the first one to reach normal will be energized to seize the line for its associated primary finder apparatus and at the same time by placing a ground thereon make the test conductor 110 test idle or non-calling to the second primary finder apparatus, as has been heretofore stated. It may be here noted that in practice the time required for a primary sequence switch to idly run through its cycle of positions, as in this case, is so comparatively short that even if no other idle primary finder seized the terminals of the calling line the delay will be so short as to place little or no drag upon the operation of the system.

During restoration of the two primary finders which have made a simultaneous attempted seizure of the calling line, the remaining idle primary line finders continue to rotate. In fact the unsuccessful idle primary line finders will continue to rotate in any event until by the operation of the switch 171 of the primary controller the ground is removed from the local conductor 111 at the front contact of the ground relay 109. During this rotation all lines that have been successfully seized will test busy on account of the ground applied by the connected successful primary finder upon the

test conductor 110 through the brush 258, all lines to which connection has been made at a selector switch will test busy on account of the ground applied to the test conductor 110 through the front contact and the armature 114 of the tone relay 108, and all lines with the terminals of which the brushes of two unsuccessful primary finders are in contact will test "calling", there being battery supplied to the test conductor of such line and no ground applied by the primary finders.

It will, of course, be understood that similar or analogous operations take place in the secondary controller finder apparatus, the intermediate finder apparatus and the final finder apparatus, whenever the brushes of two such finders simultaneously come in contact with the terminals of a "calling line." In each of these cases, however, it will be the test relay of such apparatus upon the energization of which will depend the seizure by its associated apparatus of the "calling line," and if such test relay does not operate the apparatus will be restored to normal.

In the case of an intermediate finder apparatus which must return to its normal condition owing to the failure of the intermediate test relay to attract its armature, the intermediate line relay 351 will be energized by a circuit from battery through the right winding of such relay, sequence switch contact 310, back contact and armature of the test relay 386 to ground and back to battery. This circuit will be closed from the second position through the sixth position of the intermediate sequence switch. Therefore when in the third and fourth positions of the sequence switch the hundreds selection controlling circuit would be otherwise closed this selection controlling circuit will remain open at the back contact of the armature 352 of the intermediate line relay 351. The apparatus of the associated secondary controller will therefore be in no way affected by this idle return to normal.

In a precisely similar way on the failure of the final test relay 462 to energize due to the attempted simultaneous seizure of the "calling line" by two final finders the consequent energization of the final line relay 451 from the second through the fifteenth position of the final sequence switch through the sequence switch contact 435 will prevent the closure of the tens and units selection controlling circuits at the back contact of the armature 452 of such final line relay 451.

It will be further observed that while the two unsuccessful final finders are idly returning to normal, no detrimental effect will result in the intermediate finder apparatus due to the removal of the ground from the test conductor 380 which ground has energized the intermediate line relay 351 and

thereby caused the intermediate sequence switch to move into its seventh position. This is for the reason that when once the intermediate apparatus has left its sixth position there are no controlling circuits governed by the intermediate line relay in its seventh position and the intermediate finder apparatus will remain in its seventh position until its restoration is initiated from the primary finder apparatus. Therefore the only effect of the deenergization of the intermediate line relay 351 is the placing of a ground connection again upon the local wire 382 leading to selected group of final finders. This starts again in rotation all idle final line finders of the selected group, one of which may seize the terminals of the "calling" line before the two that first attempted to seize them again reach their normal condition. In this connection it may be noted that immediately upon the original energization of the intermediate line relay which occurred when ground was placed upon the test conductor 380 through the test relay 462 of a final finder, ground was removed by the attraction of the armature 368 from the local wire 382 leading to the selected group of final finders and all "unsuccessful" final line finders stopped rotating.

Similarly in the primary finder when the primary line relay 251 was energized in the tenth position of the primary sequence switch it not only caused the sequence switch to move into its twelfth position but also removed the ground connection from the local wire 282 leading to the selected group of intermediate finders and caused all of the "unsuccessful" intermediate line finders to stop rotating.

Furthermore, as just described in connection with the intermediate finder apparatus, the deenergization and reenergization of the primary line relay 251, while the primary sequence switch is in its twelfth position, by the removal of ground through the intermediate test relays 386 of intermediate finders while such finders returning idly to normal condition produces no result save the connection and disconnection of ground connection of the local wire 282 leading to the selected group of intermediate finders, and is therefore without detrimental effect. This reconnection of the ground connection to the local conductor being for the same purpose as above described in connection with the intermediate apparatus, that is, to start the idle finders of the selected group again in rotation since no finder has as yet successfully seized the "calling" terminals.

In the case of two secondary controller line finders attempting a simultaneous seizure of the "calling" terminals of a primary finder, the test relay 558 will not attract its armature. The restoring circuit may in this

- case be traced from battery through the sequence switch 501, sequence switch contact 508, right winding of the relay 530, back contact and armature of the test relay 558 to ground and back to battery. This circuit will drive the secondary controller sequence switch into its nineteenth position from which position it will be restored to normal by the circuit through the sequence switch contact 539, the relay 530 being now deenergized. In this idle movement of the secondary controller sequence switches, however, no ground connection will be placed upon the primary finder terminal 274 by the closure of the sequence switch contact 509 as would be the case in the normal operation of the apparatus on account of there being no ground upon the sequence switch contact 509, the test relay 558 being deenergized. Therefore the primary finder sequence switch will not be moved out of its sixth position by this attempted seizure and the idle secondary controller line finders will continue to rotate until one does successfully seize the "calling" terminals. It will be furthermore observed that the energization and deenergization of the primary intermediate over the circuit including the various secondary controller test relays 558 is without effect in the sixth position of the primary finder sequence switch.
- All finders busy.*—If, when the subscriber initiates a call, all of the primary line finders happen to be engaged, the subscriber will receive busy tone precisely as in the case of premature selection hereinafter to be described, so that he will be informed that he must start his calling operation afresh. The same is true if all the secondary controllers of the particular group associated with the line finder which seizes his line should be busy at that particular time. On the other hand, if, when the thousands wet point device has been set, all of the intermediate finders associated with the test and local lines 280 and 282 of the selected group are busy, the only effect would be that the call would be held up until one of the intermediate finder apparatus reaches its normal condition, closing by its sequence switch the sequence switch contacts 303 and 304. The call will then continue as though there had been no delay, it being noted that this delay has had no effect upon the condition of the secondary controller apparatus associated with the calling line, since the selecting circuit was opened awaiting its closure through the sequence switch 312 of the intermediate finder apparatus.
- 60 The same condition of affairs will exist if, when the hundreds wet point device operated to pick out the local and test conductor to a group of final finder apparatus, all of these are busy, the call merely awaiting the restoration to normal of one of the final

finder apparatus, the selecting circuit being maintained opened during this time, and therefore affecting in no way the condition of the secondary controller apparatus.

There will be, of course, a sufficient number of finders of each character to carry the ordinary business of the system, but if under exceptional circumstances the condition should arise of all of the finders of the selected group being busy, the subscriber will be informed of the fact by the busy tone if it is a primary line finder or a secondary controller line finder. Furthermore, if it is an intermediate or a final line finder, he may either await the completion of his call which will occur when desired line finders become idle, or he may restore his receiver to its switch hook and all of the apparatus will be restored to normal, as has been heretofore described. In either event, the apparatus will act in its regular order and sequence and will at its proper time return completely to its normal condition.

Premature selection.—If by not performing the sending operations according to the instructions given, or if by any unusual or irregular act the subscriber should start the operation of his primary controller mechanism 170 before the successful primary finder sequence switch has left its fourth position, provision is made whereby such irregular operation will be taken care of and any delay which might otherwise result may be prevented. It will be noted by referring to the description of the operation of the primary finder and the secondary controller hereinbefore described that the energization of the cutoff relay 104 of the calling line occurs only after a primary finder and a secondary controller have been operatively associated with the terminals of such calling line, that is, in the seventh position of the primary sequence switch. Therefore if the switch 171 of the subscriber's primary controller 170 is operated as stated above the cutoff relay 104 being still unenergized the ground relay 109 will, being deprived of current, be deenergized. The deenergization of this ground relay will remove the ground connection from the local wire 111 leading to the primary line finders in which the terminals of this particular line appear, and, if any of such line finders are still rotating hunting for this line, will cause them to stop. The deenergization of the ground relay has also closed a circuit from the battery 113 through the front contact and armature of the subscriber's line relay 102 which is still energized through a circuit including the ground at the switch device 171, the tone relay 108 and the back contact and armature of the ground relay 109 to ground and back to battery. This causes the energization of the tone relay 108 and applies the tone connected with the front contact of such tone 130

relay to the line conductor 106 through armature 115 and back contact of the cut-off relay 104, service meter 119, of course, however, not operating the service meter. 5 When now the primary controller at the substation has completed its operation and the switch 171 is again closed, this tone circuit will be completed through the subscriber's instrument, the line conductor 105 and the 10 subscriber's line relay 102; the tone will therefore be heard by the subscriber who will know that his call has been unsuccessful and he must start his operations afresh. In connection with this attempted premature selection, it will be observed that the 15 ground applied to the test conductor individual to the calling line through the armature and front contact of the tone relay 108 will make the terminals of this line test idle 20 or non-calling to any primary finders which may be rotating in response to a call from some other subscriber's line in the same group. It will be further noted that the 25 battery applied to the multiple test terminal through the cutoff relay 104 and the front contact and armature of the subscriber's line relay 102 will make this line test busy on all of the selectors in which it appears. By 30 this means no irregular or abortive connection will be made with this line owing to the irregular operation of the subscriber's apparatus. It will be furthermore noted that this attempted premature selection will not 35 tie up or make busy any of the primary line finders or secondary controllers after the ground relay 109 has been deenergized. This is true for the reason that if the 40 attempted premature selection took place and the ground was removed from the local conductor 111 of the calling line any time while the primary sequence switch 201 was still in its first position, it merely causes the deenergization of the line relay 251 which, by the retraction of its armature 252 will cause 45 the deenergization of the hunting relay 255, the intermediate relay 261 and the finder rotary magnet 259, and the apparatus will again be in its normal condition, the brushes not as yet having found the terminals of 50 what was the calling line. If, however, the premature selection takes place during the second to fourth positions of the sequence switch 201, such sequence switch when it reached its sixth position will find an 55 energizing circuit for itself closed from battery through the sequence switch 201, sequence switch contact 238, front contact and armature 262 of the hunting relay 255 to ground and back to battery. This circuit 60 has been established by the failure to energize or the deenergization of the primary selecting relay 267 due to the absence of battery over the test conductor 110, before the primary sequence switch has left its fourth 65 position. If therefore the relay 267 deen-

ergizes or remains unenergized in the third or fourth position of the primary sequence switch a circuit will be established from battery 101 through the subscriber's line relay 102, line conductor 105, primary finder brush 264, line conductor 266, left winding of the primary test relay 286, sequence switch contact 211, back contact and armature of the relay 267 to ground and back to battery. This circuit energizes the test relay 286 which closes a locking circuit for itself and also for the hunting relay 255 through the right winding and armature of such test relay and the resistance 287. This circuit when once established will be maintained and the hunting relay remain energized until the test relay is deenergized upon the arrival of the primary sequence switch in its first or normal position which deenergization has been hereinbefore described. The primary sequence switch 201 having been driven from its sixteenth position by the circuit traced will continue to move until it reaches its eighteenth position, from which position restoration will continue, as has been before described. Immediately that the apparatus again comes into its normal position it may again be used in connection with any of the calling lines, the terminals of which appear in this line finder, the time which has been taken for it to again reach its normal position having been comparatively brief. 95

Referring back to the operation of the cutoff relay 104 of the calling line, which took place when a direct ground connection was placed upon the test conductor 110 in the seventh position of the "successful" primary finder sequence switch, it closed at its armature 115 and front contact thereof a circuit for itself independent of the armature 114 of the tone relay 108, which circuit included the resistance 118 and the front contact and armature 115. By the closure of this circuit the cutoff relay 104 will be maintained energized when the tone relay 108 is energized at the time that the switch 171 of the primary controller at the subscriber's station is operated. This substitute circuit will be maintained so long as the ground connection is maintained on the test conductor 110 from the primary finder apparatus and therefore prevents the deenergization of the cutoff relay 104 until the primary finder apparatus has begun its restoring operations. 115

The tone 117 is of any usual or well known construction and arrangement and is connected through the resistance 116, such resistance being adjusted so that it will not maintain the cutoff relay energized in series with the resistance 118 after ground has been removed from the test conductor 110 at the primary finder apparatus. 125

It will be of course understood that the 130

apparatus shown to the left of Fig. 1 is located at the subscriber's substation, whereas the apparatus shown to the right of Fig. 1 is located at the central office. It may be noted at this point that the apparatus shown to the right of Fig. 1 is all of the apparatus which is individual to a subscriber's line at the central station, all of the other apparatus at the central station being common to pluralities of lines and apportioned on any accepted percentage basis.

It will be observed that for convenience but one subscriber's line is shown herein, such line serving in the description herein for both the calling and the called subscriber's line, but it will be obvious that in an actual connection the operation will be as herein described, the called line being in all respects similar and analogous to the calling line shown herein. Each line in the exchange is designed to have its terminals appear in a plurality of primary jacks and to have its multiple conductors 197, 198 and 199 lead to and appear in a plurality of selector switches individual to the hundred lines of the particular thousand and the particular hundred in such thousand according to the designation of the line; for example, if, as has been assumed with regard to the called line, the line designation is 5149, the multiple conductors 197, 198 and 199 will appear in the selector switches appropriated to the second hundred of the sixth thousand lines of the exchange.

Referring to the register setting circuit including the relays 527 and 528 there appear in this circuit the resistances 276 and 526. These resistances are inserted in this circuit for the purpose of increasing the margin of operation of the sensitive relay 527 and such resistances are, as noted, located upon opposite sides of the armature 596 of the units transfer relay 594 which at times connects the brush 541 directly to ground. There will be furthermore observed the resistance 290 in a branch circuit leading from the register setting circuit through the back contact and armature 270 of the primary intermediate relay 261 and the back contact and armature 262 of the primary hunting relay 255 to ground. This ground connection and resistance 290 are for the purpose of maintaining substantially uniform the current flow through the subscriber's line relay 102, it being observed that this ground connection through the resistance 290 will be removed at the time that the register setting circuit including the resistances 526 and 276 is closed.

The condenser 531 and the resistance 532 in a shunt circuit around the armature and contact of the register setting relay 527 and the condenser 533 and resistance 534 in a shunt circuit around the armature and front

65 contact of the register restoring relay 529

are for the usual purpose. It will be observed that it may be advisable to use heavy current over these circuits in order to produce a positive operation of the register disks by the various register setting and 79 register restoring magnets.

In order to provide for the contingency that owing to a premature disconnection from the calling subscriber's end of the circuit, the various registers 561, 571, 581 and 591 may not be in their normal positions when the secondary controller sequence switch 501 leaves its sixteenth position, the sequence switch contacts 522, 523, 524 and 525 and a grounded interrupter connected therewith are provided. Under the circumstances stated when the secondary controller sequence switch 501 comes into its nineteenth position, the hereinbefore described energizing circuit through the sequence switch contact 539 will not exist on account of the energization of the register cutoff relay 530. This relay will be energized through a circuit which may be traced from battery through any one or more of the sets of contacts 563, 573, 583 and 593 and the left windings of their associated transfer relays 564, 574, 584 and 594 through the sequence switch contact 521, right winding of the register cutoff relay 530, armature and back contact of the test relay 558, which is at this time deenergized, to ground and back to battery. This circuit will be maintained so long as any one of the contacts 563, 573, 583 and 593 remains closed to battery, that is, 100 so long as any one of the register disks is in an off normal position. In this nineteenth position of the secondary controller sequence switch, the sequence switch contacts 522, 523, 524 and 525 are closed. A circuit will therefore be closed from battery through the respective register restoring magnets 567, 577, 587 and 597 through the respective associated sequence switch contacts and the interrupter to ground and back to battery. The operation of the interrupter, which is continuously moving, will cause the various register restoring magnets to be intermittently energized to attract and release their armatures. This operation of the register restoring armatures will continue until each of the register disks is again in its normal position and the contacts 563, 573, 583 and 593 are all open. When this occurs the energizing circuit through the right winding of the register cutoff relay 530 will be destroyed and such relay becoming deenergized will retract its armature 536. The circuit for the secondary controller sequence switch 501 through the sequence switch contact 539 is now established and the sequence switch will move into its first or normal position, all of the apparatus of the secondary controller now being entirely restored. In the restoration of the register disk just described, the stop 92 (see 130

Fig. 6) diagrammatically indicated upon Fig. 5, will prevent the movement of the register disk beyond its normal position under the control of the interrupter and the 5 register restoring relays 567, 577, 587 and 597.

Referring to Fig. 2, it may be mentioned that the resistance 287 prevents the short-circuiting of the battery connected to this 10 resistance through the sequence switch contact 215 and the back contact and armature of the primary supervisory relay 272 when, in positions 16 to 19 of the primary sequence switch after a successful call, the sequence switch contact 238 is closed.

The various sequence switches may be provided, if desired, with holding magnets such as indicated at 449 in the final sequence switch. These holding magnets may be of 15 any desired arrangement and operation, but are preferably similar in function and arrangement to the respective line finder holding magnets such as 460.

It will be observed that when a connection 20 has been completed, the talking circuit has bridged across it only the two battery supply bridges, the one including the supervisory relay 272 and the retardation coil 277, and the other including the supervisory relay 30 456 and the retardation coil 469. It will be observed that when the apparatus is in talking 45 position, the talking circuit is clear from the calling station to the called station with the exception of the non-inductive resistance 35 289 and the usual condensers 476 and 477.

The restoration of the apparatus individual to a subscriber's line, whether such line is a calling or a called line, depends upon the deenergization of the cutoff relay 104 40 which is energized over its right winding if the line is a calling line and over its left winding if the line is a called line. If the line is a calling line this deenergization will occur when ground is removed by the primary sequence switch reaching its seventeenth position and will occur if the line is a called line when ground is removed from the multiple test conductor 199 by the final sequence switch leaving its fifteenth position. The deenergization of the cutoff relay 104 in either case restores all of the subscriber's line apparatus to normal, provided the subscriber's receiver had been returned to its switch hook. Of course if the subscriber's receiver had not been restored to its switch hook, the subscriber's line relay 102 would be maintained energized and the ground relay 109 would be reenergized. This condition will start a new connection. 50 As it is highly probable, however, that the subscriber will have his receiver restored to its switch hook before the deenergization of the cutoff relay 104, this condition is not likely to occur, but if, on the other hand, he has restored his receiver to its switch hook

and desires another connection, the apparatus will without delay begin to operate, in response to this energization of the subscriber's line relay 102 and the ground relay 109.

Considering the system as a whole it will be observed that it is adapted to accomplish the interconnection of lines and trunk lines rapidly and with absolute precision. It will of course be understood that while 70 the invention has been shown as applied to a system of ten thousand lines, systems involving my invention are not confined to such number of lines, but the number of lines may be increased as may be necessary in 75 any particular case, such increase being accomplished by the insertion in the circuit and system of additional finder apparatus and associated wet point devices similar to that herein shown and described as the intermediate finder and hundreds wet point device. When such additional apparatus is inserted in the system, it will be only necessary in 80 order to control such apparatus to insert corresponding register devices and sequence switch contacts in the secondary controller apparatus shown in Fig. 5 similar to the register devices 561, 571, 581 and 591 and their associated sequence switch contacts already shown herein. As a matter of fact, 85 the secondary controller sequence switch as shown is adapted for use in connection with five registers rather than four as shown, as is indicated by the figure 8 adjacent the special contact 562. In this particular case, 90 however, since but four registers are shown, the sequence switch contact 520 is closed continuously from the sixth through the ninth position of the sequence switch 501 instead of only in the sixth position, as 95 would be the case if five registers were shown. Of course when using five registers and therefore three wet point devices, it will be necessary to have five digit dials in the primary controller 170 at the subscriber's 100 station, but since such primary controllers are well known to the art they need not be further referred to.

By reference to the circuit of the intermediate finder apparatus, Fig. 3, it may be observed that when on the retraction of the armature 354 of the intermediate hunting relay 355 in the first position of the intermediate sequence switch, the circuit is closed through the intermediate selecting relay 367 115 to energize the same, which also includes the sequence switch 301. It will furthermore be observed that upon the attraction of the armature of this intermediate selecting relay 367, another circuit is closed through the intermediate sequence switch 301, which circuit includes only the sequence switch contacts 308 and 309 and the front contact and armature of the relay 367. It might appear 120 as though this latter circuit, since it seem- 130

ingly shunts the intermediate selecting relay 367, would cause this relay to buzz, that is, rapidly attract and retract its armature and in so doing prevent the proper energization of the intermediate sequence switch 301. It has been found, however, in actual practice and in actual use of the system as shown herein, that the buzzing of this relay in no way detrimentally affects the operation of the system and that the intermediate sequence switch 301 will be properly energized by the two circuits just traced therethrough and move from its first into its third position. Similarly by reference to the final 15 finder apparatus, Fig. 4, it will be seen that the circuit closed by the retraction of the armature 458 of the final hunting relay 455 in the first position of the final sequence switch, which is established in order to move the final 20 sequence switch from its first to its third position, passes through such sequence switch and also through the resistance 471, the left winding of the final supervisory relay 456 and the sequence switch contact 425. The 25 closure of this circuit energizes the final supervisory relay 456, which attracts its armature and closes a second circuit for the final sequence switch which includes only the sequence switch contact 425 and the 30 front contact and armature of the final supervisory relay 456. It might appear that the final sequence switch 401 would not be properly energized by the closure of these 35 circuits since the attraction of its armature seemingly shunts the final supervisory relay 456 and causes it to buzz, that is, rapidly attract and retract its armature. It has been found, however, in this case also that in actual practice and in practical installations embodying the invention that the final 40 sequence switch 401 is properly energized in response to the closure of the circuits traced and moves as is necessary out of its first position and into its third position.

45 The intermediate sequence switch 301 and the final sequence switch 401 are energized in the manner just described rather than directly under the control of the armatures of the hunting relays in order that the intermediate and final test relays need not be especially quick-acting. That is to say, the control of the starting of the sequence switches referred to is relayed through the intermediate selecting relay and the final 50 supervisory relay in order that the test relays referred to may have ample time to become energized before the sequence switch leaves its first position, provided their respective finders are the only ones connected 55 with the terminals of the respective "calling" lines. It is not desired that these test relays should be particularly quick-acting, and it is by means of this relayed control which, as has been before noted has been 60 found in actual practice to work with un-

failing accuracy, that this necessity is obviated.

While I have shown the various sources of current as separate batteries it will be understood that this showing is for convenience only and in an actual installation of a system involving my invention such separate batteries where they are of the same character and located in the same exchange may be and preferably are one and the same 7 battery.

Having described my invention what I claim is:

1. In a telephone exchange system, the combination with a connecting circuit at a central station, of a plurality of groups of line finding devices each of such groups being apportioned to different groups of lines in said central office and each of such devices adapted to extend the circuit of said connecting circuit, switching apparatus associated with said connecting circuit but forming no part thereof operable to select one of said groups of devices and control the connection of one of the devices of the selected group of devices with said connecting circuit, and controlling apparatus controlling said switching apparatus.

2. In a telephone system, a connecting circuit at a central exchange, a plurality of groups of line seeking devices, each group being apportioned to a different group of lines and each device being adapted to extend said connecting circuit, automatic switching apparatus at said central station, a call initiating device at a distant station, a call storing register at the central station adjusted by impulses transmitted from the distant station, and when adjusted, controlling said switching apparatus, said switching apparatus being operable to select one of said groups of devices and control the connection of one of the selected group of devices with said connecting circuit.

3. In an automatic telephone system, a central exchange, lines terminating thereat, a switching device at said exchange, means for automatically connecting the same to a calling line, a plurality of groups of line seeking devices, a group of contacts operatively associated with each device, means permanently associating certain contacts of each group of contacts to said switching device, and means for causing one of said seeking devices of any desired group to pick the contacts connected to the switching device associated with the calling line.

4. In an automatic telephone system, a central exchange, lines terminating thereat, line finding devices at said exchange, means for automatically connecting one of said devices to a calling line, a plurality of groups of line seeking devices, a group of contacts operatively associated with each seeking device, means connecting contacts of each 1

group of contacts to each of said line finding devices respectively, and means for causing one of any desired group of line seeking devices to pick the contacts connected to the line finding device associated with the calling line.

5. In an automatic telephone system, a central station, lines terminating thereat, line finding devices at said station, means for causing said line finding devices to hunt in common for the terminals of a calling line, means for causing the line finding device first arriving at said terminals to remain in engagement therewith, groups of line seeking devices, a group of contacts operatively associated with each such device, means connecting each line finding device to contacts of each group of contacts respectively, and means for causing one of the said line seeking devices of any desired group to pick the contacts connected to the line finding device associated with the calling line.

6. In an automatic telephone system, a central station, lines terminating thereat, line finding devices at said station, means for causing said line finding devices to hunt in common for the terminals of a calling line, means for causing the line finding device first arriving at said terminals to remain in engagement therewith, groups of line seeking devices, a group of contacts operatively associated with each such device, means connecting each line finding device to contacts of each group of contacts respectively, means for causing any selected group of line seeking devices to hunt in common for the contacts connected to the line finding device associated with the calling line, and means for causing the line seeking device first arriving on said contacts to remain in engagement therewith.

7. In an automatic telephone system, a central exchange, lines terminating thereat, switching devices at said central exchange, means for automatically connecting one of said switching devices to a calling line, a plurality of groups of line seeking devices, a group of contacts operatively associated with each of said groups, means connecting 50 contacts of each group of contacts to each switching device respectively, means for

causing one of any desired group of line seeking devices to pick the contacts connected to the switching device associated with the calling line, a plurality of groups of line hunting devices, a group of terminal contacts operatively associated with each of said hunting devices, means uniting terminal contacts of each group to each line seeking device respectively, and means for 60 causing one of any desired group of line hunting devices to pick the terminal contacts of the line seeking device now associated with the calling line.

8. In an automatic telephone system, a central exchange, lines terminating thereat, line finding devices at said exchange, means for causing said line finding devices to hunt in common the terminals of a calling line, means for causing the line finding device first arriving on said terminals to remain in engagement therewith, groups of line seeking devices, a group of contacts operatively related to each line seeking device, means uniting contacts of each group of 75 contacts with each line finding device respectively, means for starting any desired group of said line seeking devices hunting for the contacts united to the line finding device associated with the calling line, means for causing the line seeking device first engaging said contacts to remain in engagement therewith, a plurality of groups of line hunting devices, a group of contact terminals operatively related to each hunting device, means uniting contact terminals of each such group with each line seeking device respectively, means for starting any desired group of said line hunting devices hunting in unison for the contact terminals 80 connected to the line seeking device associated with the calling line, and means for causing the line hunting device first arriving on said contact terminals to remain in engagement therewith.

95
In witness whereof, I hereunto subscribe my name this 25th day of October, A. D. 1910.

WILLIAM HUGO MATTHIES.

Witnesses:

FRANCIS A. COX,
EDWARD MONTCHYR.
